21 Claims. (Cl. 103—46)

The present invention relates in general to fluid operated pumps and pumping systems for wells, and particularly oil wells, and a general object of the invention is to provide improved equipment of this character.

Basically, a fluid operated oil well pump of the reciprocating type includes interconnected engine and pump piston means and includes engine valve means for alternately applying high and low pressures to opposed faces of the engine piston means so as to reciprocate the two piston means, whereby the pump piston means pumps fluid from the well upwardly through a production tubing to the surface. The operating fluid for actuating the pump, which is usually clean crude oil, is conveyed downwardly thereto at a relatively high pressure through a supply tubing set in the well, the spent operating fluid discharged by the pump at a lower pressure either being mixed with the production fluid and being returned to the surface through the production tubing, or being returned to the surface through a separate, return tubing set in the well. The fluid operated pump may be of the single acting type, or the double acting type, and various features of the present invention may be embodied in a pump of either type, although the single acting type will be considered primarily hereinafter as a matter of convenience. Fluid operated pumps are also either of the free type, or the set type, a pump of the former type being movable between its operating position in the well and the surface through the tubing system associated therewith so that removal of the tubing system in order to remove the pump is unnecessary. With a pump of the set type, on the other hand, removal of at least part of the tubing system is necessary to permit removal of the pump since the pump is attached to one of the tubes of the system. Various features of the present invention are applicable to pumps of either of these types, although pumping equipment of the free type will be considered primarily hereinafter, the invention being particularly applicable to this type.

Since the operating fluid for a fluid operated pump is delivered thereto from the surface and since the production fluid pumped thereby is delivered to the pump from therebeneath, it is conventional to locate the engine means of the pump, including the engine piston means and the engine valve means, in the upper end of the pump unit and to locate the pump means in the lower end thereof. Also, locating the pump means in the lower end of the unit is necessary in a well where the fluid level is very low in order to permit pumping the well to its full capacity. In a conventional fluid operated pump of this nature, the engine means is located at the upper end of the unit in axial alignment with the pump means. With this conventional construction, it is necessary to provide a by-pass around the engine for the production fluid, irrespective of whether the production fluid is conveyed to the surface through a production tubing in alignment with the pump, or through a production tubing spaced laterally from the axis of the pump. While such bypassing of the production flow around the engine can be

2

accomplished satisfactorily, my Patent No. 2,589,671, issued March 18, 1952, and my co-pending application Serial No. 487,303, filed February 10, 1955, now Patent No. 2,869,470 illustrating how the production flow may be by-passed around the engine into a production tubing in axial alignment with the pump, such by-passing of the production fluid nevertheless imposes problems and one primary object of the present invention is to provide a fluid operated pump wherein such problems are overcome by flowing the production fluid axially through a pump unit and directly into a production tubing in axial alignment with such unit.

Considering another phase of the invention, the engine valve or engine valve means of a fluid operated pump is the most critical component thereof from the standpoint of maintenance, the cost of repairing a fluid operated pump and the frequency with which repairs are necessary being determined primarily by the engine valve. It is probably safe to say that under average conditions, a fluid operated pump would be capable of operating twice as long without removal from the well for repairs if the service life of the engine valve could be made equal to that of the remainder of the pump. However, this is impossible to attain with engine valve materials presently available. In other words, there are no engine valve materials available at the present time which will withstand both corrosion and abrasion at the high pressures and high temperatures existing in fluid operated well pumping systems, to an extent sufficient to attain an engine valve service life anywhere near the service life of the remainder of the pump. Another primary object of the invention is to overcome the foregoing problems by making the engine valve a separate valve unit which may be removed from the well for service or repair independently of the remaining components of the pump, such remaining components being referred to hereinafter as constituting a pump unit.

Another problem which is encountered in connection with conventional fluid operated pumps of the free type is that removal of such pumps hydraulically sometimes results in intermingling of the operating fluid with the production fluid, the latter frequently containing such foreign matter as water and sand, and results in loosening products of corrosion which may line the interior of the pump tubing, i.e., the tubing through which the free pump is circulated between the surface and its operating position in the well. When such a conventional fluid operated pump is reinstalled, or a replacement pump is installed, the pump is exposed to much of this foreign material and at least some of it passes through the pump when it is first started, thereby causing excessive wear. Also, the pump may not start at all under such conditions and may have to be removed again for cleaning, and possibly further repair. In any event, the first few strokes of the pump may cause as much wear and damage, particularly to the engine valve, as months of normal operation. Still another primary object of the invention is to overcome such problems by making the engine valve a separate valve unit which is installed, operated and removed in the clean operating fluid system only so that it is impossible for foreign matter to enter the valve unit from the sources mentioned.

With the foregoing general discussion and primary objects of the invention as background, various more specific objects of the invention and various advantages of and new results attainable with the invention will now be considered.

Considering the present invention in more detail, an important object thereof is to provide a fluid operated pump which includes separate pump and valve units interconnected in fluid communication when disposed in their respective operating positions in the well, the pump unit

including interconnected engine and pump piston means and the valve unit including engine valve means for applying operating fluid pressure to the engine piston means to reciprocate the engine and pump piston means.

Another important object of the invention is to provide a fluid operated pump having separate pump and valve units wherein the valve unit is spaced laterally from and located alongside of the pump unit and wherein production fluid flow takes place through the pump unit axially thereof.

Another object is to provide a fluid operated pump having separate pump and valve units wherein the valve unit is of the free type so that it may be installed in and removed from the well readily without disturbing the tubing system.

Still another object is to provide a fluid operated pump having separate pump and valve units wherein both units are of the free type to provide for installation and removal thereof without disturbing the tubing system.

A further object is to provide a fluid operated pump including separate, free pump and valve units movable into and out of the well independently of each other or simultaneously.

Another object is to provide a free pump wherein separate valve and pump units are movable into and out of the well hydraulically through different tubings of the tubing system.

Another object is to provide a fluid operated pumping system wherein a free pump unit is movable between the surface and its operating position in the well hydraulically through a pump tubing which also serves as the production tubing, and wherein a separate free valve unit for controlling the operation of the pump unit is movable hydraulically between the surface and its operating position in the well through a valve tubing, which is preferably the supply tubing for delivering operating fluid under pressure to the pump.

By circulating the pump unit into and out of the well through the production tubing and by circulating the valve unit into and out of the well through the supply tubing, the valve unit may be removed and/or installed without exposure to foreign matter tending to produce excessive wear, and the pump unit may be installed and/or removed without exposing the valve unit to materials likely to damage it or cause excessive wear thereof. Thus, the present invention eliminates a great deal of engine valve trouble, which is an important feature of the invention.

Not only does the present invention permit separate removal of the engine valve and prevent exposure of the engine valve to foreign matter by making the engine valve a separate unit exposed only to the clean operating fluid system, but it attains various other advantages as well. For example, the invention results in a small valve unit which may be removed from the well hydraulically with a relatively small volume of operating fluid at a relatively low pressure as compared to the volume and pressure required to remove the entire pump from the well. Consequently, surface pumping equipment capable of removing the entire pump in one hour has sufficient capacity to remove the valve unit in ten minutes, or less. Also, since the valve unit is small and light, it may be displaced to the surface hydraulically without the use of any packer cups thereon to prevent or reduce fluid by-pass. As an example, a valve unit of the present invention for use with a 1 1/4 inch pump unit may be only 5/8 inch in diameter and 12 inches long and may weigh approximately 15 ounces. The hydraulic pressure required to balance this weight is only 3 p.s.i.

In addition to the other advantages mentioned, such a small valve unit has the advantage of enabling a pumper to carry enough of them in his automobile to service a large number of wells. Further, since engine valves for fluid operated pumps are precision devices which can

be repaired properly only by skilled mechanics in shops provided with precision equipment, the separate valve units of the present invention, being small and light, may be flown great distances to a properly equipped shop at small cost.

Thus, one properly equipped plant can service valve units of the present invention from every oil field in an extremely large area without excessive delay and at a lower net cost since the savings attainable as the result of a large operation more than offset the shipping costs, even by air.

Another important advantage of the present invention resulting from locating the engine valve means out of axial alignment with the engine and pump piston means, preferably in the form of a separate valve unit alongside

15 of a pump unit incorporating the engine and pump piston means, is that the production fluid pumped by the pump piston means may flow axially through the engine and pump piston means from a production fluid inlet at the lower end of the pump unit to a production fluid outlet at the upper end thereof. The pump unit is preferably axially aligned with the production tubing, and is preferably hydraulically movable therethrough between its operating position and the surface, so that the axial production fluid flow through the pump unit discharges

20 axially into the production tubing. Thus, straight-line production fluid flow through the pump unit into the production tubing is attained without any necessity for laterally by-passing the engine, which is an important feature.

25 30 An important object of the invention is to provide a fluid operated pump in which the engine or engine means is concentric with and surrounds a reduced section of a single plunger which constitutes both an engine piston means and a pump piston means.

More particularly, an object of the invention is to provide a combined engine and pump piston means incorporated in a single plunger having intermediate its ends a section of reduced diameter to provide two transverse annular areas which face each other and which 40 serve as engine areas.

Another object is to provide a fluid operated pump which includes engine valve means alongside and spaced laterally from the plunger described in the preceding paragraph for alternately applying the operating fluid pressure and the spent operating fluid pressure to at 45 least one of the transverse engine areas to produce reciprocatory movement of the plunger.

Another object is to provide a single acting, fluid operated pump the return stroke of which is produced by 50 applying either the operating fluid pressure or the spent operating fluid pressure to two oppositely facing, transverse surfaces of slightly different areas, such as slightly different engine areas formed at the ends of the reduced intermediate section of the combined engine and pump plunger mentioned.

Another object is to provide a single acting, fluid operated pump wherein the working stroke is produced by applying the operating fluid pressure and the spent operating fluid pressure to oppositely facing, transverse 55 areas, these areas being slightly different to produce the return stroke upon application of the same pressure to both.

Another object is to provide a single acting, fluid operated pump which includes a plunger movable upwardly during its working stroke and carrying a working valve, and which includes a standing valve below the plunger. Another object in this connection is to provide two standing valves, one below the plunger and one above the plunger.

70 Another object of the invention is to provide a single acting, fluid operated pump having engine valve means which includes governing means for throttling the flow of operating fluid under pressure to prevent racing of the plunger during its working stroke when the load thereon is less than a predetermined value.

Another object is to provide a single acting, fluid operated pump having a plunger with an upward working stroke and having a standing valve above the plunger and to provide such a pump with an engine valve means having governing means for controlling the plunger speed during its working stroke.

A further object is to provide a single acting, fluid operated pump having a plunger which moves downwardly during its return stroke and having a standing valve below the plunger, and to provide such a pump with an engine valve means including governing means for controlling the piston speed during the return stroke.

Another object is to provide a free valve unit for use with a separate pump unit and having a three-speed action.

Still another object is to provide a free valve unit having a governing action.

Another object is to provide a free valve unit for use with a separate pump unit and having governing means for controlling the speed of a plunger in the pump unit with a throttling action.

Still another object is to provide a free valve unit for use with a separate pump unit which governs by throttling the operating fluid flow to a plunger in the pump unit, or the spent operating fluid flow therefrom, whenever there is less than a predetermined load on the plunger during the working stroke thereof.

Still another object is to provide a free valve unit which operates with a governing action during either or both strokes of a plunger controlled thereby.

Another object of the invention is to provide a pump unit for insertion into a pump chamber wherein the pump unit has a production fluid outlet at the upper end thereof and is provided with sealing means thereon below the production fluid outlet for engagement with the wall of the pump chamber. With this construction, the sealing means prevents any sand in the production fluid discharged from the production fluid outlet from packing between the pump unit and the wall of the pump chamber, thereby facilitating removal of the pump unit from the pump chamber. A related object is to provide a production fluid outlet which includes ports above the sealing means at different levels so as to constantly agitate any sand discharged from the production fluid outlet with the production fluid.

Another object is to provide a pump which includes a pump unit having a cylinder with a plunger element therein, and which includes means for applying to the exterior of the cylinder a fluid pressure at least equal to the mean between the highest and the lowest fluid pressures applied to the interior of the cylinder. With this construction, radial expansion of the cylinder due to the internal pressure is minimized or prevented to maintain the desired clearance between the plunger element and the cylinder, which is an important feature.

The foregoing objects, advantages, features and results of the present invention, together with various other objects, advantages, features and results thereof which will be apparent to those skilled in the art in the light of this disclosure, may be attained with the exemplary embodiments of the invention which are illustrated in the accompanying drawings and which are described in detail hereinafter. Referring to the drawings:

Figs. 1, 2, 3 and 4 are diagrammatic views respectively showing different fluid operated pump units of the invention;

Figs. 5, 7, 9, 11 and 13 are diagrammatic views of different fluid operated pumps of the invention each including a pump unit and a valve unit side-by-side;

Fluid operated pump units 41 to 44

30 Respectively illustrated in Figs. 1, 2, 3 and 4 of the drawings are single acting, fluid operated pump units 41, 42, 43 and 44 of the invention. Each of these pump units includes combined or interconnected engine and 35 pump piston means embodied in a single tubular plunger 46 having an axial production fluid passage 48 therethrough, each of the plungers 46 including upper and lower plunger elements 50 and 52 respectively reciprocable in upper and lower cylinders 54 and 56 and interconnected by a hollow rod or tube 58 reciprocable in a bore or cylinder 60 interconnecting the cylinders 54 and 56. Thus, the plunger 46 in each of the pump units 41 to 44 is in effect provided with an intermediate section of reduced diameter. With this construction, upper and 40 lower annular, transverse engine areas 62 and 64 are provided at the lower end of the upper plunger element 50 and the upper end of the lower plunger element 52, respectively, transverse areas 66 and 68 being provided at the upper end of the upper plunger element and the 45 lower end of the lower plunger element, respectively. The diameter of the upper plunger element 50, designated by the dimensional arrow 70, is slightly less than the diameter of the lower plunger element 52, designated by the dimensional arrow 72. With this construction, the lower engine area 64 is slightly larger than the upper engine area 62, thereby providing each plunger 46 with a small annular, differential engine area which faces upwardly for a purpose to be described. The diameter difference between the plunger elements 50 and 52 may 50 be quite small, e.g., a few thousandths of an inch, and is therefore not readily apparent in the drawings, although it is shown therein.

55 In each of the pump units 41 to 44, the plunger 46 carries a working valve 74 which opens upwardly to 60 permit upward flow of production fluid through the axial passage 48 from an inlet 76 to an outlet 78 in response to downward movement of the plunger, the working valve closing to prevent back flow through the axial passage 48 in response to upward movement of the plunger. Thus, 65 in each of the pump units 41 to 44, the upward stroke of the plunger 46 is the working stroke thereof and the downward stroke of the plunger is the return stroke thereof, in the particular construction illustrated. In 70 each instance, the working valve 74 is a simple ball valve engageable with a valve seat 80 carried by the plunger 46.

and encircling the axial passage 48 therethrough. In the pump units 41 and 43, the working valves 74 are at the upper ends of the passages 48, while in the pump units 42 and 44, the working valves 74 thereof are shown as located within the plungers 46.

The pump units 41 and 43 are provided with standing valves 82 above the corresponding plungers 46 and adjacent the corresponding outlets 78, these standing valves being shown as simple ball valves engageable with valve seats 84. In each of the pump units 42 and 44, a standing valve 86 is provided below the corresponding plunger 46 and adjacent the corresponding inlet 76, the standing valves 86 also being shown as simple ball valves engageable with valve seats 88. Each of the standing valves 82 and 86 opens upwardly in response to upward movement of the corresponding plunger 46, and closes in response to downward movement thereof.

Considering the manner in which the working and return strokes of the plungers 46 of the pump units 41 to 44 are produced, associated with, and preferably located alongside of each pump unit, is a valve unit comprising an engine valve or engine valve means for controlling the application of pressure to either or both of the engine areas 62 and 64 of each plunger, these valve units being omitted from Figs. 1 to 4 of the drawings, but being illustrated in detail in subsequent figures of the drawings and being described in detail hereinafter. Also omitted from each of Figs. 1 to 4 for convenience is a source of operating fluid at a high pressure and a point of disposal for spent operating fluid at a lower pressure, these being illustrated in subsequent figures and being described in detail hereinafter.

Considering now the pump units 41, 42 and 44, the operating fluid pressure is constantly applied to the upper engine areas 62, the operating fluid pressure and the spent operating fluid pressure being applied to the lower engine areas 64 alternately by the associated valve units and to be described. In each of the pump units 41, 42 and 44, the plunger 46 moves upwardly through its working stroke when the spent operating fluid pressure is applied to the lower engine area 64, and moves downwardly through its return stroke when the operating fluid pressure is applied to the lower engine area 64, the return stroke occurring with the operating fluid pressure applied to both the upper and lower engine areas 62 and 64 because of the fact that, as hereinbefore discussed, the lower engine area 64 is slightly larger than the upper engine area 62 to provide a small, annular, upwardly facing, net differential area on which the operating fluid pressure acts to produce the return stroke. This net differential area may be quite small since it is necessary to overcome frictional forces only in producing the return stroke of the plunger of the pump units 41, 42 and 44.

With regard to the pump units 41 and 43, in each of these the lower engine area 64 of the plunger 46 may also be constantly exposed to the spent operating fluid pressure, instead of being exposed to the operating fluid pressure and the spent operating fluid pressure alternately. The upper engine area 62 in each of the pump units 41 and 43 is exposed to the spent operating fluid pressure and the operating fluid pressure alternately, instead of being constantly exposed to the operating fluid pressure. Thus, in each pump unit 41 and 43, the working stroke of the plunger 46 is produced when the upper engine area 62 is exposed to the operating fluid pressure, and the return stroke is produced when the upper engine area is exposed to the spent operating fluid pressure. Again, the latter occurs because of the fact that, when the spent operating fluid pressure is applied to both the upper and lower engine area 62 and 64, it acts downwardly on a small, annular, upwardly facing, net differential area resulting from the diameter difference between the upper and lower plunger elements 50 and 52.

As in the case of the pump units 42 and 44, this net differential area may be quite small since it is necessary to overcome only friction forces during the return stroke of the plunger 46 of each of the pump units 41 and 43.

- 5 It should be noted, however, that since the spent operating fluid pressures may be less than the pumped fluid pressure, no net downward force is produced in the pump units 42 and 44 when spent operating fluid pressure is applied to the areas 62 and 64, and, hence, the units 10 42 and 44 will operate on the down stroke only when operating pressure is applied to area 64. Each of the units 41 to 44 may be operated by applying operating pressure constantly to the area 62 and alternately to the area 64, but only the units 41 and 43 may be operated 15 by applying spent operating fluid pressure constantly to the area 64 and alternately to the area 62.

It will be noted that each of the pump units 41 to 44 thus includes an engine or engine means which is actually built right into the pump plunger 46, i.e., the engine

- 20 is concentric with and surrounds an intermediate, reduced-diameter section of the pump plunger. The working and return strokes of the plunger 46 are effected by constantly applying one of the operating and spent operating fluid pressures to one of the engine areas 62 and 25 64 and by alternately applying these pressures to the other of the engine areas, the return stroke occurring when the same pressure is applied to both engine areas because of the upwardly facing net differential between these areas. The present invention thus provides a compact engine and pump piston means combination, which is an important feature of the invention. Also, since the engine areas 62 and 64 are annular areas smaller than the areas 66 and 68, each of the pump units 41 to 44 30 utilizes a volume of operating fluid which is smaller than the volume of production fluid pumped thereby, which is another feature of the invention.

It should also be noted that, in each of the pump units 41 to 44, the production fluid flows from the inlet 76 to the outlet 78 straight through the combined engine and

- 40 pump piston means by way of the axial passage 48. In other words, since the valve unit for each of the pump units 41 to 44 is located out of axial alignment therewith as hereinafter described, the production fluid flows directly and axially through each pump unit, preferably 45 into a production tubing, not shown in Figs. 1 to 4 of the drawings, connected to the outlet 78 in axial alignment with the pump unit. With this construction, there is no necessity to provide a lateral production fluid bypass around the engine or engine means, or any part 50 thereof, which is an important feature of the invention.

Hereinafter, pump units similar to the pump units 41 to 44 will be considered in connection with valve units incorporating engine valves providing either a three speed action, or a three speed, governing action. Engine valves

- 55 having a three speed action are disclosed in detail in my prior Patent No. 2,134,174, and engine valves having a three speed, governing action are disclosed in my Patents Nos. 2,311,157, 2,473,864, and 2,580,657. Generally speaking, a three speed engine valve includes a 60 valve member which is moved between two extreme positions at three different speeds in the course of reversing the direction of motion of an engine piston means controlled thereby, while a three speed, governing engine valve governs the motion of the engine and pump piston means when the load on the pump piston means is less 65 than a predetermined value by throttling the admission of operating fluid to, or the exhausting of spent operating fluid from, the cylinder means in which the engine piston means is disposed, all of this being described in detail in the aforementioned prior patents and being described at least generally hereinafter. As pointed out earlier herein, important objects of the present invention 70 are to provide separate valve units for use with the pump units 41 to 44, or pump units similar thereto, which have actions of the character mentioned.

With the foregoing general background in mind, it might be well to point out at this juncture that each of the pump units 41 to 44 is preferably controlled by a valve unit incorporating an engine valve having at least a three speed action, although an engine valve providing a governing action may also be utilized. Considering the pump unit 41, if a governing action is applied to this pump, the governing action must take place during the working stroke of the plunger 46. If the working stroke is accomplished by constantly applying operating pressure to the area 62, thus the governing is accomplished by throttling the discharge of spent operating fluid from above the lower plunger element 52 to an extent sufficient to maintain the pressure applied to the lower engine area 64 approximately equal to the operating fluid pressure, until such time as the load on the plunger 46 attains a predetermined value. Such a governing action applied to the pump unit 41 will keep the plunger 46 from attaining an excessive speed during its working stroke in the event that no load is applied to the area 66 thereof. Such a no-load condition may result from presence of air or gas in the cylinder 54 below the standing valve 82. In the absence of a governing action, the presence of such air or gas would permit the plunger 46 to race upwardly until it reaches the upper end of its working stroke, or until it suddenly strikes solid fluid. Similar considerations are applicable to the pump unit 43 except that, in this pump unit, the governing action must occur as the result of throttling the application of the operating fluid pressure to the upper engine area 62 during the working stroke of the plunger 46.

In the pump units 42 and 44, governing must occur during the downward or return strokes of the plungers 46 due to the fact that the plungers of these units carry the full production column pressures thereabove. As will be apparent, the reason for this is that the units 42 and 44 are not equipped with standing valves above the plungers 46, but are equipped with the standing valves 86 therebelow. Consequently, the presence of air or gas in the lower cylinders 56 of the pump units 42 and 44 below the plungers 46 thereof could, in the absence of governing, result in downward racing of these plungers until such time as they either reach the ends of their return strokes, or strike solid fluid. If a governing action is utilized in connection with the pump unit 42 or 44, the governing action must occur during the return stroke by throttling the application of the operating fluid pressure to the lower engine area 64 to an extent sufficient to maintain the pressure applied to this area approximately equal to the spent operating fluid pressure.

Fluid operated pump 90

Referring now to Figs. 5 and 6 of the drawings, diagrammatically illustrated therein is a fluid operated pump 90 of the invention which included a pump unit 92 and a separate valve unit 94 located side-by-side. The pump unit 92 is identical to the pump unit 41 except that it is provided with the standing valve 86 engageable with the seat 88 below the plunger 46, in addition to the standing valve 82 above the plunger. This construction is advantageous, particularly if the valve unit 94 comprises a three speed, non-governing engine valve, which is the case. Similar considerations are applicable to the embodiments of the invention hereinafter disclosed, various ones of such embodiments being illustrated as provided with standing valves 82 and 86 respectively above and below the plunger 46. The advantage of two standing valves, one above the plunger 46 and the other therebelow, is that, in the event of pump off, the resulting high fluid velocities are confined to the pump unit itself. With only a single standing valve below the plunger, the entire production column above the plunger would move down with the plunger if no solid fluid were in the space between the plunger and the lower standing valve. By pro-

viding a standing valve above the plunger 46, as well as therebelow, this reverse movement of the production column would be prevented, with the result that only the plunger would move at a high speed. Thus, the use of standing valves above and below the plunger 46 is particularly advantageous in the case of a non-governing valve. However, the use of two standing valves is also advantageous in the case of a governing valve since it reduces the load on the piston tending to cause racing of the piston, and thus reduces the amount of governing necessary.

The pump 90 is shown as having supply, return and production tubings 96, 98 and 100 connected thereto, the supply tubing 96 conveying operating fluid under high pressure downwardly to the pump, the return tubing 98 conveying spent operating fluid at a lower pressure upwardly from the pump 90 to the surface, and the production tubing 100 being in axial alignment with the pump unit 92 and in communication with the outlet 78 thereof and serving to convey production fluid upwardly from the pump unit to the surface. While the pump 90 is thus shown as incorporated in a closed system wherein the spent operating fluid is returned to the surface independently of the production fluid by way of the return tubing 98, it will be understood that the invention is in many instances applicable to an open system wherein the spent operating fluid is mixed with the production fluid and conveyed to the surface through the production tubing. To convert the system shown from a closed system to an open system, it is merely necessary to connect the return tubing 98 to the production tubing 100 above the upper standing valve 82. Similar considerations are also applicable to each of the embodiments hereinafter disclosed, each of these embodiments being illustrated as incorporated in a closed system, but being usable in an open system also.

The pump unit 92 and the valve unit 94 are, as hereinbefore mentioned, merely shown diagrammatically in Figs. 5 and 6 of the drawings, and are not specifically shown as removable through tubings of the tubing system 96, 98, 100. However, the pump and valve units 92 and 94, which are shown as axially aligned with the production and supply tubings 100 and 96, respectively, may be moved between their operating positions in the well and the surface through the production and supply tubings, respectively, important objects of the invention being, as hereinbefore pointed out, to provide a pump having pump and valve units which are movable between their operating positions and the surface either independently of each other, or simultaneously. Such movement of the pump and valve units may be produced hydraulically, or otherwise. Similar considerations are applicable to the embodiments disclosed in Figs. 7 to 14 of the drawings, Figs. 15 to 32 being devoted to an illustrative embodiment wherein all of the structure necessary to attain the foregoing is disclosed in specific detail. Consequently, it will be understood that while the pump and valve units shown in Figs. 5 to 14 of the drawings are not specifically disclosed as movable between their operating positions and the surface through tubings of the associated tubing systems, it is within the scope of the present invention to provide for such movement, utilizing a specific structure corresponding to that illustrated in Figs. 15 to 32 of the drawings.

Considering the pump 90 now in more detail, the valve unit 94 includes a valve member 102 which is reciprocable in a bore 104 in a valve body 106 between two extreme positions, respectively shown in Figs. 5 and 6 of the drawings. The upward, or working, stroke of the plunger 46 occurs when the valve member 102 is in its upper position, as shown in Fig. 5, and the return stroke of the plunger occurs when the valve member is in its lower position, as shown in Fig. 6.

The upper engine area 62 of the plunger 46 is always

exposed to the operating fluid pressure through a passage 108 which connects the lower end of the cylinder 54 to the supply tubing 96. When the valve member 102 is in its upper position, as shown in Fig. 5, it applies the spent operating fluid pressure to the lower engine area 64 by connecting the upper end of the cylinder 56 to the return tubing 98, as will be described hereinafter. Under such conditions, the plunger 46 moves upwardly through its working stroke. Conversely, when the valve member 102 is in its lower position, as shown in Fig. 6, it connects the upper end of the cylinder 56 to the supply tubing 96, which applies operating fluid pressure to the lower engine area 64, thereby producing the return stroke of the plunger 46. Movement of the valve member 102 between its upper and lower positions is controlled by grooves 110 and 112 in the reduced-diameter section of the plunger 46, i.e., in the hollow rod 58 interconnecting the upper and lower plunger elements 50 and 52. The manner in which the valve member 102 controls the movement of the plunger 46, and the manner in which the plunger in turn controls the movement of the valve member, may best be disclosed by considering the structure and operation of the valve unit 94 more or less concurrently in view of the diagrammatic nature of the showing of the pump 90.

Referring to Fig. 5, when the plunger 46 reaches the upper end of its working stroke, the groove 112 in the reduced section of the plunger interconnects a passage 114 and a control passage 116, the former leading to the return tubing 98 and the latter communicating with a branch passage 118 which leads to the lower end of the valve bore 104. In the branch passage 118 is a check valve 120 which opens in a direction to permit fluid flow out of the lower end of the valve bore 104 only. Consequently, when the groove 112 bridges the passages 114 and 116, the lower end of the valve bore 104 is connected to the return tubing 98 so that fluid can escape from beneath the valve member 102 past the check valve 120. When this occurs, the valve member 102 starts to move downwardly under the influence of the operating fluid pressure in the supply tubing 96 constantly applied to the upper end of the valve member. The valve member 102 is a differential-area valve member, including at its upper end a section 122 of reduced diameter reciprocable in a bore 124 and spaced from the body of the valve member by a stem 126. The lower end of the reduced diameter section 122 and the upper end of the body of the valve member 102 communicate with an annular space 165 around the stem 126, this space being constantly connected to the return tubing 98 by a passage 166.

Under the foregoing conditions, the valve member 102 moves downwardly at the first of its three speeds, this speed being relatively high since fluid flow from the lower end of the valve bore 104 to the return tubing 98 by way of the branch passage 118, the passage 116, the groove 112 and the passage 114 is relatively unrestricted. As the valve member 102 continues to move downwardly, the lower end thereof eventually covers the end of the branch passage 118 which communicates with the bore 104, such end of the branch passage being located a predetermined distance above the extreme lower end of this bore. When this occurs, communication between the lower end of the valve member 102 and the return tubing 98 by way of the avenue hereinbefore described is cut off. At the same time, however, the lower end of an external annular groove 128 in the valve member 102 registers with a passage 130 leading to the return tubing 98. Under such conditions, the lower end of the valve member 102 communicates with the return tubing 98 through the passage 130, the annular groove 128, a helical groove 132 in the exterior of the valve member, an external annular groove 134 in the valve member, and passages 136 and 138 through

the valve member, the passage 138 leading to the lower end of the valve member. With these conditions obtaining, the valve member 102 continues to move downwardly, but at a reduced speed, this second speed being controlled by the area of the helical groove 132, which throttles fluid flow to provide considerable flow resistance. The throttling groove 132 may simply be a thread formed on the exterior of the valve member 102.

When the valve member 102 reaches the end of its downward movement at the reduced second speed controlled by the throttling groove 132, an external annular groove 140 in the valve member registers with a passage 142 leading to the return tubing 98. A throttling or metering hole or orifice 144 in the valve member 102 connects the annular groove 140 to the passage 136. Under such conditions, the lower end of the valve member 102 is connected to the return tubing 98 through the passage 138, a portion of the passage 136, the throttling hole 144, the annular groove 140 and the passage 142. The resistance offered by the throttling hole 144 determines the third downward speed of the valve member 102, this third downward speed being higher than the second downward speed thereof. Actually, the third speed is determined by the helical groove 132 plus the throttling hole 144, but the latter predominates.

Considering now how the valve member 102 controls the pump unit 92 as the valve member moves downwardly at the three different speeds discussed above the valve member moves downwardly at its first, high speed until such time as V ports or throttling grooves 122a in the reduced section 122 thereof begin to uncover a passage 146 leading from the bore 124 to the upper end of the cylinder 56. Thereafter, the valve member 102 moves downwardly at its second, slow speed, under the control of the throttling groove 132, so that the operating fluid pressure from the supply tubing 96 is applied through the passage 146, to the lower engine area 64 of the plunger 46 slowly. Consequently, the plunger 46 is slowly accelerated in the downward direction to initiate its return stroke. As soon as the plunger 46 has been accelerated to some extent in this manner, the annular groove 140 in the valve member 102 registers with the passage 142 to initiate the third speed of downward movement of the valve member. The third speed of the valve member is substantially higher than the second speed thereof so as to fully uncover the passage 146 rapidly after initial downward acceleration of the plunger 46, thereby permitting the plunger 46 to attain its maximum speed with minimum resistance to flow through the passage 146.

The foregoing discussion thus explains the manner in which the plunger 46 initiates downward movement of the valve member 102 and the manner in which the downward movement of the valve member occurs, at three successively different speeds, to reverse the upward movement of the plunger and to produce the return stroke thereof. With the foregoing events completed, the valve member 102 is in its lower position and the plunger 46 is moving downwardly as illustrated in Fig. 6 of the drawings.

When the plunger 46 reaches the lower end of its return stroke, the groove 110 in the reduced section of the plunger connects the lower end of the upper cylinder 54, which is always connected to the supply tubing 96 through the passage 108, to the control passage 116. Communicating with the passage 116 is a branch passage 148, an external annular groove 150 in the valve member 102 registering with this passage when the valve member is in its lower position. The valve member 102 is provided with a passage 152 therein which connects the groove 150 to the passage 138 through a check valve 154. This check valve permits fluid to flow from the passage 152 into the passage 138, but not in the opposite direction. Thus, the lower end of the valve member 102 is placed in communication with the supply tubing 96 through the passage 138, the check valve 154, the passage 152, the annular

groove 150, the branch passage 148, the passage 116, the groove 110 and the passage 108. Consequently, the valve member 102 starts to move upwardly since the operating fluid pressure is applied to an area at the lower end thereof which is larger than the area of the upper end of the reduced section 122 of the valve member. Such upward movement of the valve member 102 is at a relatively high speed, this being the first speed of upward movement of the valve member.

After the valve member 102 has moved upwardly at its first speed a predetermined distance, the annular groove 150 therein moves out of communication with the passage 148 to cut off communication between the supply tubing 96 and the lower end of the valve member by way of the avenue hereinbefore described. When this occurs, an annular groove 158 in the exterior of the valve member registers with a port 160 which, in turn, communicates with the supply tubing through a passage 162. The annular groove 158 communicates with the annular groove 134 through a helical throttling groove 164 corresponding to the throttling groove 132. Under these conditions, the lower end of the valve member 102 is placed in communication with the supply tubing 96 through the passage 138, the passage 136, the annular groove 134, the throttling groove 164, the annular groove 158, the port 160 and the passage 162. The throttling groove 164, which may merely be a helical thread in the exterior of the valve member 102, determines the second speed of upward movement of the valve member, this second speed being relatively low.

The second speed of the valve member 102 in the upward direction begins as V ports or throttling grooves 122b in the lower end of the reduced section 122 of the valve member start to uncover the passage 146. As this occurs, application of spent operating fluid pressure to the lower engine area 64 of the plunger 46 is initiated through the passage 146, through the annular space 165 around the stem 126 interconnecting the body of the valve member and the reduced section 122 thereof, and through the passage 166 leading from the annular space 165 to the return tubing 98. Thus, as the valve member 102 moves upwardly at its slow second speed, the pressure applied to the lower engine area 64 of the plunger 46 is slowly reduced to the spent operating fluid pressure, whereby the plunger 46 is accelerated upwardly slowly. Thus, the throttling groove 164 controls the upward acceleration of the plunger 46 during the second, slow speed of upward movement of the valve member 102.

As soon as the plunger 46 has been accelerated upwardly somewhat, the valve member 102 begins its third speed of upward movement, which is higher than its second speed, to uncover the passage 146 rapidly so as to permit the plunger to attain its maximum upward speed. Considering how this is accomplished, when the annular groove 140 in the valve member 102 registers with a passage 168, communicating with the passage 162, operating fluid may flow to the lower end of the valve member 102 by way of the passage 162, the passage 168, the annular groove 140, the metering or throttling hole 144, a portion of the passage 136 and the passage 138. The metering hole 144 determines the third upward speed of the valve member 102, which is substantially higher than the second upward speed thereof to uncover the passage 146 rapidly once the plunger 46 has received its initial upward acceleration.

Thus, the foregoing describes how the arrival of the plunger 46 at the end of its return stroke initiates upward movement of the valve member 102, and how this upward movement of the valve member continues at three successively different speeds to reverse the direction of movement of the plunger 46 so as to produce the working stroke thereof.

It should be noted that the control passage 116 determines the first speed of the valve member 102 in both directions. The direction in which the valve member

102 moves upon connection of the grooves 110 and 112 to the control passage 116 is determined by the check valves 120 and 154. In other words, when the groove 112 connects the control passage 116 to the return tubing 98, the check valve 120 opens to permit downward movement of the valve member 102. On the other hand, when the groove 110 connects the control passage 116 to the supply tubing 96, the check valve 154 opens to permit upward movement of the valve member.

10 It will be understood that while the fluid operated pump 90 has been described as incorporating the standing valve 86, in the pump unit 92 thereof, this standing valve may be omitted. In other words, the pump unit 41 could be substituted for the pump unit 92, and the 15 operation of such a pump unit in conjunction with the valve unit 94 would be the same as hereinbefore described.

Fluid operated pump 170

20 Referring now to Figs. 7 and 8 of the drawings, illustrated therein is a fluid operated pump 170 of the invention which includes a pump unit 172 and a separate valve unit 174 disposed in side-by-side relation. The pump unit 172 is identical to the pump unit 42 described previously, except that the standing valve 82, engageable with the valve seat 84, has been added thereto. The valve unit 174 is identical to the valve unit 94.

25 The important difference between the pump 170 and the pump 90 is that in the pump 170 the working valve 74 is in the lower plunger 52 so the clearance volume of the bottom of the stroke is small. In the pump 90 the working valve 74 is in the upper plunger 50 so the clearance volume is small at the top of the stroke.

30 Since the valve unit 174 is identical to the valve unit 94 and since the pump unit 172 is very similar to the pump unit 92, the operation of the pump 170 will be apparent from the foregoing description of the operation of the pump 90.

35 It will be understood that the upper standing valve 82 may be omitted from the pump unit 172, thereby making this pump unit identical with the pump unit 42. With this substitution, the pump unit and the valve unit 174 would still operate in the same manner as hereinbefore described in connection with the fluid operated pump 90. Consequently, a further description herein is 40 unnecessary.

Fluid operated pump 180

45 Illustrated in Figs. 9 and 10 of the drawings is a fluid operated pump 180 which again includes a pump unit 182 and a valve unit 184 in laterally spaced relation, the pump unit 182 being identical to the pump unit 41, except that it includes the standing valve 86 engageable with the valve seat 88. The valve unit 184 comprises a three speed engine valve which governs during both strokes of the plunger 46. While the double standing valve arrangement illustrated in Figs. 9 and 10 is preferable for the reasons hereinbefore indicated, either the pump unit 41 or the pump unit 42 may be substituted for the pump unit 182.

50 55 60 65 The valve unit 184 is similar to the valve unit 94, except that it adds a governing action during both strokes of the three speed action of the valve unit 94. In view of this similarity, identical reference numerals will be utilized in connection with the valve unit 184 insofar as possible and the valve unit 184 will be considered primarily on the basis of the differences between it and the valve unit 94.

60 65 The valve member 102 of the valve unit 184, instead of being provided with the reduced section 122, is provided with a longer reduced section 186 connected to the body of the valve member by a relatively short stem 188. The reduced section 186 is provided therein with a relatively wide annular channel 190 which connects the supply tubing 96 to the passage 146 leading to the lower engine area 64 of the plunger 46 when the valve member

102 is in its upper position, as shown in Fig. 9, and which connects the passage 166 from the return tubing 98 to the passage 146 to apply the spent operating fluid pressure to the lower engine area 64 when the valve member 102 is in its lower position, as shown in Fig. 10. Consequently, the plunger 46 moves downwardly when the valve member 102 is in its upper position, and the plunger moves upwardly through its working stroke when the valve member is in its lower position, this being just the reverse of the interaction between the plunger 46 and the valve member 102 in the fluid operated pump 90. When the plunger 46 reaches the end of its return stroke, the groove 110 therein bridges the passage 114 leading to the return tubing 98 and a passage 192 leading to the hereinbefore described branch passages 118 and 148. Such bridging of the passages 114 and 192 initiates downward movement of the valve member 102 by connecting the lower end thereof to the return tubing 98 in the manner hereinbefore described. Referring to Fig. 10, when the plunger 46 reaches the upper end of its working stroke, the groove 112 in the reduced section of the plunger bridges the passage 192 and a passage 194 leading to the supply tubing 96 through a portion of the passage 108. This connects the lower end of the valve member 102 to the supply tubing 96 through the passage 108, the passage 194, the groove 112, the passage 192, the branch passage 148, the groove 150, the passage 152, the check valve 154 and the passage 138, thereby initiating upward movement of the valve member 102 in much the same manner as hereinbefore described in connection with the valve unit 94.

Thus, it will be apparent that the first speeds of the valve member 102 are the same as for the non-governing valve unit 94, except that they occur in response to movement of the plunger 46 in reversed directions. The second speeds of the valve member 102 of the valve unit 184 are also the same as for the valve unit 94, except for the reversed directions of movement of the plunger 46. The desired governing action during both strokes is accomplished by the third speed control of the valve member 102, as will now be described.

Considering Fig. 9 of the drawings, the passage 146 is provided with an extension 198 which communicates with ports 200 and 202 leading to the valve bore 104. Considering upward movement of the valve member 102, as the valve member moves upwardly at its second speed, the upper edge of the groove 140 starts to register with the port 200, thereby connecting the lower end of the valve member 102 to the cylinder 56 above the lower plunger element 52 by way of the passage extension 198, the port 200, the groove 140, the passage 136 and the passage 138. Under these conditions, the lower end of the valve member 102 is also connected to the supply tubing 96 through the passage 162, the port 160, the throttling groove 164, the annular groove 134, the passage 136 and the passage 138.

The reduced section 186 of the valve 102 has V ports or throttling grooves 122a and 122b which throttle the fluid at the start of the stroke. The slow motion of the valve starts when the small ends of the V ports are in line with the leading edge of the annular channel 190 and the annular passage 165. The third speed in the governing valve starts when the "governing line" A—A and the "governing line" B—B are in line with the leading edges of the annular passages 190 and 165, respectively. At this point the areas of the V ports determine the maximum speed or "governing speed" of the piston 46, which may be varied by varying the V ports to shift the governing lines A—A and B—B vertically. The passages 200 and 202 are located so that the leading edges of these passages will line up with the annular grooves 128 and 140, respectively, when the lines A—A and B—B are in line with annular passages 190 and 165 respectively. Therefore, if there is no load on the plunger 46 in either direction of movement, there will be a large pressure

drop across the V ports and hence the pressure in the passages 146, 198, 200 and 202 will differ from the pressure on the other side of the valve 186.

Assuming that the area of the upper end of the reduced section 186 of the valve member 102 is one-half the area of the lower end of the valve member, if the pressure drop mentioned in the preceding sentence is equal to one-half of the difference between the operating fluid pressure in the supply tubing 96 and the spent operating fluid pressure in the return tubing 98, then the pressure applied to the lower end of the valve member is this mean pressure. Consequently, the axial forces applied to the valve member are balanced and the valve member cannot move upwardly past the position under consideration. However, as soon as the plunger 46 encounters solid fluid so that some load is applied thereto, the speed of the plunger will decrease so that the pressure drop across the V ports will decrease a corresponding amount. Such a decrease in this pressure drop results in an increase in the pressure applied to the lower end of the valve member 102 to cause the valve member to resume its upward movement. Eventually, the valve member 102 moves upwardly sufficiently to permit the channel 190 in the reduced section 186 thereof to provide normal communication between the supply tubing 96 and the lower engine area 64 by way of the passage 146. Thus, during the downward stroke of the plunger 46, the valve member 102 governs by throttling the application of operating fluid pressure from the supply tubing 96 to the lower engine area 64 until such time as the load on the plunger 46 attains a predetermined value.

Considering the governing action during the working stroke of the plunger 46, when the plunger reaches the end of its return stroke prior to beginning its working stroke, the groove 110 in the reduced section of the plunger bridges the passages 114 and 192 to connect the lower end of the valve member 102 to the return tubing 98 through the passage 114, the groove 110, the passage 192, and the passage 118. Thus, the valve member 102 starts moving downwardly at its first speed, and subsequently moves downwardly at its second, slow speed, all as hereinbefore described. As in the case of governing during the return stroke of the plunger 46, governing during the working stroke thereof is accomplished through the third speed control for the valve member 102. The third speed of downward movement of the valve member 102 as the plunger 46 begins its working stroke normally results from registering of the annular groove 140 with the port 202, which places the metering hole or orifice 144 in communication with the passage extension 198 leading to the lower engine area 64. Under such conditions, the plunger 46, in moving upwardly, must discharge fluid into the return tubing 98 through the passage 146, the V ports 122b, the annular groove 165 and the port 166. If there is no load on the plunger 46 during its working stroke, a large pressure drop across the throttling ports 122b will exist and, therefore, the pressure applied to the lower engine area 64 will be higher than the spent operating fluid pressure in the return tubing 98. The same pressure is also applied to the lower end of the valve member 102 through the passages 198 and 202 and the throttle hole 144, and, if this pressure is equal to the mean between the operating fluid pressure in the supply tubing 96 and the spent operating fluid pressure in the return tubing 98, the forces applied to the valve member are balanced and the valve member will not move downwardly. Consequently, the plunger 46 will move upwardly at a reduced speed, controlled by the throttling ports 122b, until it hits solid fluid in the cylinder 56 above the plunger element 50. As this occurs, the pressure drop through the throttling ports 122b will decrease, which will lower the pressure applied to the lower end of the valve member 102 to a value less than the mean between the operating fluid pressure and the spent operating fluid pressure. This will

enable the valve member 102 to continue its downward movement at its third speed. Thus, governing during the working stroke of the plunger 46 is provided by throttling the discharge of fluid from above the lower engine area 64 to the return tubing 98, the pressure applied to the lower engine area being maintained substantially equal to the operating fluid pressure until such time as the plunger strikes solid fluid after having compressed any air or gas present in the cylinder 54 above the plunger element 50.

If the pump unit 182 is filled with solid fluid, the pressure drop across the throttling ports 122a will be low as the valve member 102 moves upwardly and, therefore, the pressure in the passage extension 198 will approach the operating fluid pressure as the valve member 102 moves upwardly into its upper position. Similarly, the pressure drop across the throttling ports 122b will be low as the valve member 102 moves downwardly into its lower position and, therefore, the pressure in the passage extension 198 will approach the spent operating fluid pressure. Under such conditions, the third speeds of the valve member 102 would be the same as they would be without governing. Thus, governing occurs only when the load on the plunger 46 is less than a predetermined value.

Although the valve unit 184 has been described as governing during both strokes of the plunger 46, it should be pointed out that governing during the upward or working stroke is desirable only if the pump valve arrangement incorporated in the pump unit 41 is used, and governing on the downward stroke is desirable only if the pump valve arrangement of the pump unit 42 is used, or if the pump valve arrangement of the pump unit 182 is used, i.e., if the two standing valves 82 and 86 are used. There is no necessity for governing during the downward stroke of the plunger 46 except when the lower standing valve 86 is used without an upper standing valve 82, as in the case of the pump unit 42. If the lower standing valve 86 is omitted, governing during the upward or working stroke only can be obtained by connecting the port 202 to the return tubing 98, instead of to the passage extension 198. Thus, with this simple change, which is illustrated in Figs. 11 and 12 of the drawings, the valve unit 184 can be made to govern during the upward stroke of the plunger 46 only.

Fluid operated pump 210

Figs. 11 and 12 of the drawings illustrate a fluid operated pump 210 of the invention which again includes a pump unit 212 and a valve unit 214 in side-by-side relation. The pump unit 212 is identical to the pump unit 43, except that it additionally includes the standing valve 86 engageable with the valve seat 88. The valve unit 214 includes a valve member 102 which is identical to the valve member of the valve unit 184, the only differences between the valve unit 214 and the valve unit 184 residing in the porting external to the valve member. For the sake of uniformity, identical reference numerals will be applied to the valve unit 214 insofar as possible.

As hereinbefore discussed in connection with the pump unit 43, the spent operating fluid pressure is constantly applied to the lower engine area 64 of the plunger 46 of the pump unit 212, this being accomplished through a passage 216 interconnecting the upper end of the cylinder 56 and the return tubing 98. The operating fluid pressure and the spent operating fluid pressure are alternately applied to the upper engine area 62 through the passage 108 under the control of the valve member 102 to produce the upward and downward strokes of the plunger, respectively. As shown in Fig. 11, when the valve member 102 is in its upper position, the annular channel 190 in the reduced section 186 of the valve member connects the passage 108 to the supply tubing 96 to produce the upward or working stroke of the

plunger 46. Conversely, when the valve member 102 is in its lower position, as shown in Fig. 12, the annular channel 190 connects the passage 108 to the passage 166 leading to the return tubing 98. Under such conditions, the spent operating fluid pressure is applied to the upper engine area 62 so that the spent operating fluid pressure acting on the difference between the upper and lower engine areas 62 and 64 produces the downward, or return, stroke of the plunger 46, as hereinbefore described. The manner in which the valve member 102 is displaced between its upper and lower positions to accomplish the foregoing will now be considered, the valve member providing a governing action during the upward stroke of the plunger 46 only.

Referring to Fig. 12 of the drawings, as the plunger 46 reaches the end of its return stroke, the groove 110 in the hollow rod 58 bridges passages 218 and 220, the former communicating with the supply tubing 96 and the latter communicating with the branch passages 118 and 148. Thus, operating fluid pressure from the supply tubing 96 is applied to the lower end of the valve member 102 through the passage 218, the groove 110, the passage 220, the branch passage 148, the annular groove 150, the passage 152, the check valve 154 and the passage 138, thereby moving the valve member upwardly at its first upward speed. The second upward speed of the valve member 102 begins when the annular groove 150 moves out of register with the branch passage 148. At this time, the groove 158 in the valve member registers with the port 160 communicating with the supply tubing 96 through the passage 162. Under these conditions, operating fluid from the supply tubing 96 is delivered to the lower end of the valve member 102 through the passage 162, the port 160, the annular groove 158, the throttling groove 164, the annular groove 134, the passage 136 and the passage 138. Thus, the resistance offered by the throttling groove 164 determines the slow second speed of the valve member.

Considering the governing action during the upward stroke of the plunger 46, as the valve member 102 moves upwardly, the annular groove 140 therein begins to register with the port 200, this port being connected, by a passage 222, to the passage 108 controlled by the annular channel 190 and leading to the upper engine area 62. If there is no load on the plunger 46 when the annular groove 140 begins to register with the port 200, the pressure in this port will be low, due to the pressure drop in the V ports 122a, which are in a position such that the line A—A is in register with the upper edge of the valve body at 122c, so that a large pressure drop will exist across the throttling ports 122a in response to flow of operating fluid from the supply tubing 96 through the passage 108 into the cylinder 54 below the upper piston 50. Since the lower end of the valve member 102 is exposed to the low pressure in the port 108 through the passage 222, the port 200, the annular groove 140, the hole 144, the passage 136 and the passage 138, the valve member 102 will not move upwardly as long as the pressure applied to the lower end thereof is equal to the mean between the operating fluid pressure and the spent operating fluid pressure, again assuming that the area of the upper end of the reduced section 186 is equal to one-half of the area of the lower end of the valve member 102. When the plunger 46 hits solid fluid, the aforementioned pressure drop through the throttling ports 122a will decrease, thereby increasing the pressure applied to the lower end of the valve member to cause it to resume its upward movement. This upward movement of the valve member 102 takes place at the third speed, which is determined by the metering hole 144, to connect the upper engine area 62 to the supply tubing 96 rapidly so as to enable the plunger 46 to attain its normal upward speed. Thus, the governing action during the upward stroke of the plunger 46 takes

place as the result of throttling the application of operating fluid pressure to the upper engine area 62 to an extent sufficient to maintain the pressure applied to the upper engine area approximately equal to the spent operating fluid pressure constantly applied to the lower engine area 64 until such time as the plunger hits solid fluid after having compressed any air or gas present.

Considering initiation of the downward stroke of the plunger 46 with reference to Fig. 11 of the drawings, when the plunger 46 reaches the upper end of its working stroke, the groove 112 in the reduced section thereof connects the passage 216 to the passage 220. Consequently, the lower end of the valve member 102 is exposed to the spent operating fluid pressure, or exhaust pressure, through the passage 118, the check valve 120, the passage 220, the groove 112 and the passage 216, the latter leading to the return tubing 98. Consequently, the valve member 102 moves downwardly at its first speed. Eventually the downwardly moving valve member 102 covers the end of the passage 118 in communication with the bore 104 to terminate the first-speed movement. At this time, the annular groove 128 in the valve member registers with the passage 130 leading to the return tubing 98, whereby the lower end of the valve member is exposed to the spent operating fluid pressure through the passage 130, the annular groove 128, the throttling groove 132, the annular groove 134, the passage 136 and the passage 138. Thus, the valve member moves downwardly at its second, slow speed, which is determined by the throttling groove 132. At the end of the downward movement of the valve member 102 at its second, slow speed, by which time the plunger 46 will have been accelerated downwardly, the annular groove 140 in the valve member registers with a port 224 leading to the return tubing 98. Consequently, the lower end of the valve member 102 is now exposed to the spent operating fluid pressure through the port 224, the annular passage 130, the metering orifice 144, the passage 136 and the passage 138. The valve member now moves downwardly at its third speed to fully open communication between the upper engine area 62 and the return tubing 98 through the passage 108, the annular channel 190 and the passage 166, the third speed being determined by the metering orifice 144. Thus, there is no governing action during the downward stroke of the plunger 46.

It should be pointed out that the port 224 corresponds to the alternative location for the port 202 hereinbefore described in connection with the discussion of the pump 180. Replacing the port 202 of the pump 180 with the port 224 of the pump 210 will render the valve unit 184 of the pump 180 non-governing during the downward stroke of the plunger 46.

Fluid operated pump 230

Illustrated in Figs. 13 and 14 of the drawings is a fluid operated pump 230 of the invention which includes a pump unit 232 and a valve unit 234 in laterally spaced, side-by-side relation. The pump unit 232 is identical to the pump unit 44. The valve unit 234 is identical to the valve unit 184, except that the port 202 is omitted and a port 224 connected to the passage 98 is added. The port 224 is in the same location as and performs the same function as in the pump 210.

Provision of the port 200 results in governing during the down stroke of the plunger 46, instead of governing during the working stroke thereof. It is thought that the manner in which the provision of the port 200 results in governing during the downward stroke of the plunger 46 will be apparent from the previous description. Consequently, a further description herein is unnecessary.

General

From the foregoing, it will be apparent that the present

invention contemplates various pump units including various combinations of working and standing valves and including plungers reciprocable by various applications of operating fluid pressure and spent operating fluid pressure thereto. It will also be apparent that the invention contemplates valve units including engine valves having various actions, including three speed actions on both strokes of the plunger, a governing action on both strokes, a governing action during the working stroke only with a three speed action during the return stroke, and a governing action on the return stroke only with a three speed action during the working stroke. As hereinbefore discussed, these pump units and valve units may be used in various combinations. In each instance, the hereinbefore discussed advantages of making the valve unit a separate unit spaced laterally from the pump unit, and preferably located alongside of the pump unit, are attained.

Any of the foregoing combinations of pump and valve units may be incorporated in a fluid operated free pump in which the pump and valve units are movable between their operating positions in the well and the surface through the tubing system 96, 98, 100, the pump and valve units having the operative relationships hereinbefore described when both are in their operating positions in the well. The pump and valve units of such a fluid operated free pump may be moved between their operating positions and the surface independently of each other or in unison in accordance with the present invention, the advantages of making the valve unit removable from the well independently of the pump unit having been discussed previously herein. While the pump and valve units may be installed in and removed from the well through the tubing system in various ways, as by means of wire lines, hydraulic installation and removal are preferable and such modes of installation and removal will be considered hereinafter for illustrative purposes.

Thus, it will be understood that while only one free pump unit and free valve unit combination will be described hereinafter in specific detail in connection with Figs. 15 to 32 of the drawings, and of the pump units and valve units hereinbefore described may be substituted therefor to attain the same general results. For convenience, the installation illustrated in Figs. 15 to 32 includes a fluid operated free pump corresponding to the fluid operated pump 90 illustrated in Figs. 5 and 6. In other words, the fluid operated free pump incorporated in the installation illustrated in Figs. 15 to 32 includes a free pump unit corresponding to the pump unit 92, and includes a three speed, non-governing, free valve unit corresponding to the valve unit 94. Reference numerals for the foregoing components of the fluid operated free pump illustrated in Figs. 15 to 32 of the drawings will be assigned hereinafter.

Figs. 15 to 32

Referring particularly to Fig. 15 of the drawings the present invention is illustrated therein as installed in a well which is provided with a casing 240, the casing having perforations 242 through which well fluid may flow into the casing from surrounding productive formations, not shown. The supply, return and production tubings 96, 98 and 100 are suspended in the casing 240 from a casing-head 244 at the surface and are connected at their upper ends to a control device 246. Also connected to the control device 246 are supply, return and production lines 248, 250 and 252. The supply line 248 is connected to a suitable source of operating fluid under pressure, such as surface pumping equipment, not shown, while the return and production lines 250 and 252 are connected to suitable points of disposal, not shown, for the spent operating fluid and the production fluid. When pump and valve units to be described hereinafter are in operation in the well, the control device

246 connects the supply, return and production tubings 96, 98 and 100 to the supply, return and production lines 248, 250 and 252, respectively, the control device 246 being provided with valve means therein not shown, actuatable by a handle 254 to accomplish this. However, under other circumstances, such as removal and/or installation of the pump unit and/or valve unit, the handle 254 may be actuated to cause the control device 246 to perform other functions which will be described hereinafter.

Connected to the supply, return and production tubings 96, 98 and 100 and enclosing the lower ends thereof is a gas anchor 256. Within this gas anchor and connected to the lower ends of the tubings 96, 98 and 100 is a bottom hole assembly 258 having therein a pump chamber 260, Figs. 19 to 23, and a valve chamber 262, Figs. 21 and 22. The pump chamber 260 is axially aligned with and communicates with the production tubing 100, while the valve chamber 262 communicates with and is axially aligned with the supply tubing 96. The pump chamber 260 is adapted to receive a free pump unit 264, Fig. 15 and Figs. 19 to 23, which corresponds to the pump unit 92, and the valve chamber 262 is adapted to receive therein a free valve unit 266, Figs. 15, 21 and 22, which corresponds to the valve unit 94. The pump unit 264 is movable between the pump chamber 260 and the surface hydraulically, as will be described hereinafter, and is engageable at the surface by a pump catcher, not shown, carried by a removable closure 268 on the control device 246 in alignment with the production tubing 100. Similarly, the valve unit 266 is movable hydraulically, as will be described, between the valve chamber 262 and the surface through the supply tubing 96, and may be removed from the supply tubing upon removal of a closure 270 on the control device 246 in alignment with the supply tubing. With the foregoing general background in mind, the bottom hole assembly 258 and the pump and valve units 264 and 266 will now be considered in more detail.

Considering the general elements of the bottom hole assembly 258, this assembly includes a tubular packer nose housing 272, Figs. 19 and 20, threaded onto the lower end of the production tubing 100, an upper pump housing tube 274 being threaded into the lower end of the packer nose housing. The bottom hole assembly 258 also includes a packer collar 276, Fig. 21, having a major bore 278 therethrough into the upper end of which is threaded the lower end of the pump housing tube 274. The upper end of a lower pump housing tube 280 is threaded into the lower end of the major bore 278, the lower end of this pump housing tube being threaded into the upper end of a major bore 282 through a bottom shoe 284, Fig. 23. Lock nuts 286 and 288 are threaded on the pump housing tube 280 and are seated against the packer collar 276 and the bottom shoe 284, respectively, as more fully disclosed in my copending application, Serial No. 487,303, filed February 10, 1955, now Patent No. 2,869,470 various structural features of the bottom hole assembly 258 being disclosed and claimed in the copending application just mentioned. Threaded into the lower end of the major bore 282 through the bottom shoe 284 is an inlet tube 290 through which fluid from the well is admitted into the bottom hole assembly 258 for pumping, by the pump unit 264, upwardly through the production tubing 100 into the production line 252.

Continuing to consider the bottom hole assembly 258, the lower end of the supply tubing 96 is threaded into the upper end of a minor, valve bore 292, Fig. 21, through the packer collar 276, the valve unit 266 being movable through the supply tubing 96 into the valve bore 292 and into the valve chamber 262, which is located within this bore as hereinafter described. Threaded into the lower end of the valve bore 292 is a tube 294 which forms part of the valve chamber 262,

5 a tube 296 being threaded into the lower end of the tube 294, as shown in Fig. 22. Referring to Fig. 23, the lower end of the tube 296 extends into a minor bore 298 in the bottom shoe 284, the tube 296 being sealed relative to the bottom shoe by an O-ring 300. In a similar manner, the lower end of the return tubing 98 is threaded into the upper end of another minor bore 302 through the packer collar 276 in a manner not specifically shown, the minor bore 302 being visible in Figs. 10 to 29 of the drawings. Threaded into the lower end of the minor bore 302 is a tube 304, Figs. 18 and 23, the lower end of which extends into another minor bore 306 in the bottom shoe 284 and is sealed relative thereto in the same manner as the tube 296.

15 Considering the pump chamber 260 in more detail, pressed into a reduced bore 310, Fig. 20, at the lower end of the packer nose housing 272 is an upper sealing collar or sleeve 312 having radial ports 314 therethrough for the discharge of production fluid into the packer nose housing. The sealing collar 312 may be regarded as defining a portion of the pump chamber 260, other portions thereof above and below this sealing collar being defined by the packer nose housing 272 and the upper pump housing tube 274, respectively. Moving to Fig. 21, 20 another portion of the pump chamber 260 is defined by an intermediate sealing collar 316, hereinafter termed a packer collar sleeve, disposed in the upper portion of the major bore 278 through the packer collar 276. The packer collar sleeve 316 is provided with various ports 25 therethrough which interconnect the pump and valve chambers 260 and 262 which will be described hereinafter. Proceeding downwardly, another portion of the pump chamber 260 is defined by a lower sealing collar 318, Fig. 23, disposed in the upper portion of the major bore 282 through the bottom shoe 284 and seated against the lower end of the lower pump housing tube 280. The interior of the sealing collar 318 communicates with the minor bore 298 in the bottom shoe 284 through an internal annular groove 320 in the sealing collar, radial ports 30 322 therein, an internal annular groove 324 in the bottom shoe 284 and a passage 326 in the bottom shoe. As will be discussed in somewhat more detail hereinafter, this communication between the interior of the sealing collar 318 and the bore 298, which latter communicates with the tube 296, has for one of its purposes the establishing 35 of fluid communication between well fluid pressure and a bottom hole pressure gauge 328, Fig. 22, which may be connected to the lower end of the valve unit 266. Also, in many instances the pressure gauge 328 may not be used and a dummy extension of the valve unit 266 may be substituted therefor under such circumstances. For convenience, the element 328 will hereinafter be termed an extension of the valve unit 266.

40 Returning to Fig. 23, seated against the lower end 55 of the lower sealing collar 318 is a sleeve 330 disposed in the major bore 282 of the bottom shoe 284. The interior of this sleeve communicates with the minor bore 306 in the bottom shoe, for a purpose to be described, through radial ports 332, in the sleeve, an internal annular groove 334 in the bottom shoe, and a passage 336 in the 50 bottom shoe. Clamped between the lower end of the sleeve 330 and the upper end of the inlet tube 290 is a seat 338 for a standing valve assembly 340 which provides a seat 342 for the pump unit 264. The standing valve assembly 340 is very similar to one disclosed and claimed 55 in my co-pending application, Serial No. 527,971, filed August 12, 1955, and, accordingly, will not be considered in detail herein.

Considering the free pump unit 264, at the upper end thereof, Figs. 19 and 20, is a packer nose assembly 352 70 which includes a solid packer mandrel 354 having thereon at least one downwardly facing packer cup 356. When the pump unit 264 is in its operating position in engagement with the seat 342, the packer cup 356 is disposed in the packer nose housing 272, which is sufficiently

enlarged to permit production fluid pumped by the pump unit to flow upwardly therewith into the production tubing 100. However, when the pump unit 264 is unseated and moved upwardly by pressure applied therewithin in a manner to be described, the packer cup 356 enters the production tubing 100 and makes a relatively fluid-tight seal therewith. Consequently, continued application of fluid pressure beneath the pump unit 264 results in continued movement thereof up the production tubing 100 to the surface, the packer cup engaging the production tubing to prevent fluid by-passing. The packer mandrel 354 is provided at its upper end with a tapered nose 358 which is engageable by the pump catcher carried by the closure 268 when the pump unit reaches the surface.

The lower end of the packer mandrel 354 is threaded into a coupling 360 which cooperates with the packer mandrel to house the standing valve 82 and its seat 84 described previously, the lower end of the packer mandrel providing a cage 362 for the standing valve 82. Production fluid discharged by the free pump unit 264 flows through an axial passage 364 in the coupling 360, past the standing valve 82 and through radial ports 366 in the packer mandrel into an annular space 368 between the packer mandrel and the coupling. From this annular space, the production fluid may flow through radial ports 370 and an external annular groove 372 in the coupling 360 into the radial ports 314 through the upper sealing collar 312, or it may flow from the annular space 368 into the packer nose housing 272 through radial ports 374 in the coupling 360.

The coupling 360 is encircled by an O-ring 376 which engages the upper sealing collar 312 in a fluid-tight manner when the free pump unit 264 is in its operating position, wherein it is seated on the seat 342. This O-ring performs two important functions, the first of which will now be considered and the second of which will be considered hereinafter. Since the production fluid discharged into the packer nose housing 272 through the ports 314 and 374 may contain sand, the O-ring 376 prevents such sand from settling downwardly between the pump unit and the upper pump housing tube 274. In the absence of the O-ring 376, sand might pack around the pump unit between it and the pump housing tube 274 to such an extent as to make hydraulic removal of the pump unit impossible. Also, since production fluid is discharged through the ports 314, as well as through the ports 374, any sand present is kept in motion and will flow upwardly with the production fluid, thereby preventing sand from settling in the space between the coupling 360 and the packer nose housing 272.

Threaded onto the lower end of the coupling 360 and retaining the O-ring 376 thereon is an upper plunger tube 378 having therein a liner 380 which forms the upper cylinder 54. Reciprocable in the upper cylinder 54 is the upper plunger element 50 of the plunger 46, this plunger element being provided at its upper end with the working valve 74 and the working valve seat 80. These elements are retained by a cage 382 threaded onto the upper end of the upper plunger element 50. As previously described, the working valve 74 permits upward flow of production fluid through the axial passage 48, but prevents downward flow therethrough. The hollow rod 58 forming the reduced section of the plunger 46 is threaded into the lower end of the upper plunger element 50 and, as shown in Fig. 21, is threaded into the upper end of the lower plunger element 52.

Referring to Fig. 21, the lower end of the upper plunger tube 378 is threaded onto the upper end of a tubular manifold coupling 384 which registers with the packer collar sleeve 316 when the free pump unit 264 is in its operating position, the manifold coupling having a liner 386 therein intermediate the ends thereof. The manifold coupling 384 is provided, above the liner 386, with radial ports 388 and an external annular groove 390 communicating therewith. When the pump unit 264 is in

its operating position, the groove 390 communicates with radial ports 392 leading to an external annular groove 394 in the packer collar sleeve 316, the annular groove 394 being connected to the minor bore 292 in the packer collar 276 by a passage 396 in the packer collar. The bore 292, the passage 396, the groove 394, the ports 392, the groove 390 and the ports 388 form the passage 108 for constantly connecting the upper engine area 62 to the supply tubing 96.

Considering the second function performed by the O-ring 376, there is sufficient clearance between the manifold coupling 384 and the packer collar sleeve 316 above the annular groove 390 in the manifold coupling for operating fluid to leak upwardly into the annular space between the upper pump housing tube 274 and the upper plunger tube 378. Therefore, this annular space, which is closed at its upper end by the O-ring 376, is filled with operating fluid at the pressure existing in the supply tubing 96 when the pump unit 264 is in operation. Consequently, the upper plunger tube 378 and the liner 380 forming the upper cylinder 54 are always exposed to an inward pressure equal to the operating fluid pressure. Thus, the operating fluid pressure constantly applied to the upper engine area 62 below the upper plunger element 50 is balanced in the radial direction. Since the cylinder 54 is never subjected to an internal pressure higher than the external pressure applied thereto, the clearance between the upper plunger element 50 and the liner 380 will never exceed the clearance originally provided, which is an important feature.

Below the annular groove 390 the manifold coupling 384 carries O-rings 398, 400 and 402 which engage the packer collar sleeve 316, when the pump unit 264 is in its operating position, to separate various passages which will be described hereinafter. The liner 386 is provided with external longitudinal grooves 404 therein which communicate at their upper ends with the operating fluid pressure constantly applied to the upper engine area 62, and which communicate with radial ports 406 leading to the O-ring grooves in the manifold coupling 384 behind the O-rings 398, 400 and 402. Thus, the operating fluid pressure constantly urges these O-rings outwardly into sealing engagement with the packer collar sleeve 316.

Threaded onto the lower end of the manifold coupling 384 is a lower plunger tube 408 containing a liner 410 which defines the lower cylinder 56 containing the lower plunger element 52. As shown in Fig. 23, the lower end of the lower plunger tube 408 is threaded onto a tubular coupling 412 carrying the lower standing valve 86 and its seat 88, the standing valve 86 being enclosed by a cage 414 threaded into the coupling 412. O-rings 416 and 418 engageable with the lower sealing collar 318 are carried by the coupling 412 respectively above and below an external annular groove 420 in the coupling. When the pump unit 264 is in its operating position, the groove 420 registers with the previously described groove 320, the coupling having therein one or more ports 422 leading from the interior of the coupling to the groove 420. Thus, when the valve unit extension 328 previously described comprises a bottom hole pressure gauge, the well fluid pressure is applied thereto through the ports 422, the annular groove 420, the annular groove 320, the ports 322, the annular groove 324, the passage 326, the bore 298, and the tube 296. Threaded into the lower end of the coupling 412 is an inlet plug 424 which forms the lower end of the pump unit 264 and which is adapted to seat on the pump unit seat 342 provided by the standing valve assembly 340. Thus, fluid from the well flows upwardly through the standing valve assembly 340, the inlet plug 424 and the coupling 412 and past the lower standing valve 86, the well fluid then moving upwardly through the pump unit 264 to be discharged thereby into the production tubing 100 as production fluid, all in the manner hereinbefore described.

Referring to Fig. 21 of the drawings, the manifold coupling 384 is provided therein with radial ports 426 below the lower end of the liner 386, these ports communicating with an external annular groove 428 in the manifold coupling. The groove 428 is located below the lowermost O-ring 402 carried by the manifold coupling and, when the pump unit 264 is in its operating position, this groove communicates with ports 430 in the packer collar sleeve 316 leading outwardly to an annular groove 432 in this sleeve. As shown in Figs. 21 and 27, communicating with the annular groove 432 is a passage 434 in the packer collar 276, this passage 434 communicating with a longitudinal passage 436 in the packer collar.

As will be described in more detail hereinafter, the pressure in the passage 436 is alternately the operating fluid pressure in the supply tubing 96 and the spent operating fluid pressure in the return tubing 98, the valve unit 266 producing this alternation between the operating fluid pressure and the spent operating fluid pressure. Thus, the lower engine area 64 at the upper end of the lower plunger element 52 is alternately exposed to the operating fluid pressure and the spent operating fluid pressure through the passage 436, the passage 434, the annular groove 432, the ports 430, the annular groove 428 and the ports 426. This alternating pressure is transmitted downwardly from the annular groove 428 through a leakage clearance between the packer collar sleeve 316 and the manifold coupling 384 into an annular space between the lower pump housing tube 280 and the lower plunger tube 408, which annular space is closed at its lower end by the O-ring 416, Fig. 23. Consequently, when the operating fluid pressure is applied to the lower engine area 64, fluid tends to leak into the annular space between the lower pump housing tube 280 and the lower plunger tube 408, and when the spent operating fluid pressure is applied to the lower engine area, fluid tends to leak out of this annular space. Consequently, the pressure in the annular space between the tubes 280 and 408 is a mean pressure intermediate the operating fluid pressure and the spent operating fluid pressure. The application of such a mean pressure to the exterior of the lower plunger tube 408 results in at least a partial balance between the forces acting radially on the interior and exterior of the lower cylinder 56. Consequently, variations in the desired clearance between the lower plunger element 52 and the lower cylinder 56 are minimized, which is an important feature of the invention.

Turning now to a general consideration of the valve unit 266, since it corresponds to the valve unit 94 described previously, the same reference numerals will be utilized insofar as possible. The valve unit 266 is disposed in the valve chamber 262 when the valve unit is in its operating position, the valve chamber 262 being formed by a valve chamber sealing sleeve 440 disposed in the minor bore 292 in the packer collar 276, as shown in Figs. 21, 30 and 31 in particular. The extension 328 of the valve unit 266 extends downwardly into the tube 294 and is provided with a tapered lower end 442 which engages a complementary valve unit seat 444 clamped between the tubes 294 and 296. When the valve unit extension 328 comprises a bottom hole pressure gauge, it is exposed to the well fluid pressure obtaining in the tube 296 in the manner hereinbefore described. The tapered lower end 442 of the valve unit extension 328 facilitates insertion of the valve unit into the valve chamber sealing sleeve 440 when the valve unit is being run into the well.

Referring particularly to Figs. 30 and 31 of the drawings, the valve unit 266 includes the valve body 106. The valve body includes a tube 446 having threaded onto the upper end thereof a fitting 448 which retains within the upper end of the tube 446 an internal sleeve 450. This sleeve provides the bore 124 for the reduced section 122 of the valve member 102, the upper end of the reduced

section 122 being exposed to operating fluid pressure through an axial passage 451 in the fitting 448. The valve body 106 also includes an external sleeve 452 pressed on the lower end of the tube 446 and retained by a plug 454 threaded into the lower end of the tube 446. The plug 454 is threaded into the valve unit extension 328 to secure the valve body 106 to such extension. The valve body 106 carries O-rings 456, 458 and 460 which separate various passages to be described.

The check valve 120, Fig. 31, seats on the plug 454 and is retained by a cage 462 disposed in the tube 446 and fitting over the plug 454. The check valve 154 carried by the valve member 102 seats on a plug 464 inserted into the lower end of the valve member, forming a cage 465 for this check valve.

When the valve member 102 is in its lower position, as shown in Figs. 30 and 31, operating fluid under pressure may flow downwardly from the supply tubing 96 through the bore 292 and the fitting 448 into the bore 124 above

the reduced section 122 of the valve member. Under these conditions, the reduced section is below an internal annular groove 466 in the sleeve 450, this groove communicating with radial ports 468 and 470 which extend through the sleeve 450 and the tube 446, respectively,

and which lead to an external annular groove 472 in the tube 446. Communicating with the groove 472 are radial ports 474 in the sealing sleeve 440, these ports communicating with an external annular groove 476 in the sealing sleeve. As best shown in Fig. 25, a passage 478 in the

packer collar 276 connects the annular groove 476 with the previously described longitudinal passage 436 through the packer collar. Thus, with the valve member 102 in its lower position so that the reduced section 122 thereof is below the groove 466, operating fluid under pressure

may flow through the groove 466, the ports 468 and 470, the groove 472, the ports 474, the groove 476, the passage 478, the passage 436, the passage 434, the groove 432, the ports 430, the groove 428 and the ports 426 to the lower engine area 64 of the plunger 46, the foregoing ports and passages constituting the passage 146 of

Figs. 5 and 6 of the drawings. Under these conditions, the plunger 46 moves downwardly, as hereinbefore described.

When the valve member 102 is in its upper position so that the lower end of the reduced section 122 thereof is above the annular groove 466, the passage 146 leading to the lower edge of the area 64 communicates with an internal annular groove 480 in the sleeve 450 by way of the bore 124 in which the reduced section 122 is disposed.

The annular groove 480 communicates with radial ports 482 and 484 in the sleeve 450 and the tube 446, respectively, the ports 484 communicating with an external annular groove 486 in the tube 446. Radial ports 488, Figs. 26 and 30, in the sealing sleeve 440 connect the

groove 486 to an external annular groove 490 in the sealing sleeve, and this groove communicates with a passage 492 in the packer collar 276 which leads to the bore 302 in the packer collar. As previously explained, the upper end of this bore communicates with the return tubing 98 so that it always contains fluid at the spent operating fluid pressure.

Thus, when the reduced section 122 of the valve member 102 is above the annular groove 466, the passage 146 leading to the lower engine area 64 is connected to the return tubing 98 through the groove 480, the ports 482 and 484, the groove 486, the ports 488, the groove 490, the passage 492 and the bore 302, this collection of elements forming the passage 166 shown in Figs. 5 and 6 of the drawings. Under such conditions, the plunger 46 moves upwardly through its working stroke, as hereinbefore described.

Referring now to Figs. 21 and 26 of the drawings, the passage 492, which always contains fluid at the spent operating fluid pressure, extends to the major bore 278 in the packer collar 276, and communicates with an

external annular groove 494 in the packer collar sleeve 316. Radial ports 496 through this sleeve lead inwardly to an external annular groove 498 in the manifold coupling 384. Radial ports 500 in this coupling connect the annular groove 498 to counterbores 502 in the liner 386, this liner having radial ports 504 therethrough communicating with the counterbores 502. It will be noted that the passages 302 and 492, the annular groove 494, the ports 496, the groove 498, the ports 500, the counterbores 502 and the ports 504 provide the passage 114 shown in Figs. 5 and 6 of the drawings for conveying spent operating fluid to the grooves 110 and 112 in the rod 58 interconnecting the plunger elements 50 and 52. (Actually, the rod 58 of the pump unit 264 presently under consideration is provided with external flats thereon forming channels 110 and 112 therein, instead of longitudinal grooves, the same reference numerals being utilized for better correlation with the diagrammatic representations of Figs. 5 and 6 of the drawings.) When the plunger 46 is at the upper end of its stroke, the channel 112 registers with the ports 504, and thus registers with the inner end of the passage 114. Similarly, the channel 110 registers with the ports 504, and thus with the inner end of the passage 114, when the plunger 46 is at the lower end of its stroke.

Considering now the elements of the embodiments presently under consideration which make up the control passage 116, and referring particularly to Figs. 21 and 25 of the drawings, the liner 386 is provided therein with radial ports 510 which form the inner end of the control passage 116 and which are connected in communication with the ports 504 by the channel 110 when the plunger 46 is in its lowermost position, and by the channel 112 when the plunger is in its uppermost position. The ports 510 communicate at their outer ends with counterbores 512 in the liner 386, which counterbores register with the inner ends of radial ports 514 in the manifold coupling 384. An external annular groove 516 in the coupling 384 communicates with the ports 514 therein and registers with the inner ends of radial ports 518 in the packer collar sleeve 316 when the pump unit 264 is in its operating position. An external annular groove 520 in the packer collar sleeve communicates with a passage 522, Fig. 25, in the packer collar 276, and this passage registers with a longitudinal passage 524, Figs. 25, 26, 27 and 28, in the packer collar. As shown in Figs. 21, 28 and 31, the longitudinal passage 524 communicates with a transverse passage 526 in the packer collar 276, the passage 526 leading to the valve bore 292 in the packer collar. The valve chamber sealing sleeve 449 is provided therein with an external annular groove 528 registering with the passage 526, and is provided therein with longitudinal grooves 530 which communicate with and extend downwardly from the annular groove 528. The foregoing elements define the control passage 116, the longitudinal grooves 530 constituting the junction of the branch passages 118 and 148 with the passage 116.

Considering the branch passage 118 with reference to Fig. 31 of the drawings, it includes radial ports 534 in the sealing sleeve 449 which connect the lower ends of the longitudinal grooves 530 with an external annular groove 536 in the plug 454 of the valve body 106. The annular groove 536 communicates with a transverse passage 538, the latter communicating with the lower ends of vertical passages 540 in the plug 454. The passages 540 terminate on one side of the check valve 120, the plug 454 having therein an axial passage 542 which is located on the opposite side of the check valve 120 and one end of which forms a seat for the check valve. The lower end of the axial passage 542 communicates with a transverse passage 544 in the plug 454, the ends of this passage 544 communicating with an annular groove 546 in the plug 454. Radial ports 548 and an external annular groove 550 in the cage 462 connect the annular

groove 546 to radial ports 552 in the tube 446. The ports 552 communicate at their outer ends with longitudinal grooves 554, Figs. 31 and 32, in the tube 446 of the valve body 106, these grooves communicating with the outer ends of ports 556 through the tube 446. The ports 556 constitute the inner end of the branch passage 118 and are located a predetermined distance above the lower end of the valve bore 104 to terminate the first speed of downward movement of the valve member 102, as hereinbefore described.

Considering now the branch passage 148, it includes radial ports 560, Fig. 31, which extend inwardly through the sealing sleeve 449 from the grooves 530, and which register with an external annular groove 562 in the sleeve 452 of the valve body 106 when the free valve unit 266 is in its operating position. The annular groove 562 communicates with radial ports 564 in the valve body sleeve 452, and these ports communicate with the lower ends of external longitudinal grooves 566, Figs. 31 and 32, in the valve body tube 446. The tube 446 is provided with radial ports 568 therethrough at the upper ends of the grooves 566, and these ports form the inner end of the passage 148, the annular groove 150 in the valve member 102 coming into register with the ports 568 as the valve member moves from its upper position downwardly toward its lower position.

The passage 152 in the valve member 102 includes radial ports 570, Fig. 31, therein which communicate at their outer ends with the groove 150 and which communicate at their inner ends with an annular groove 572 in the plug 464. The annular groove 572 communicates with the ends of a transverse passage 574 in this plug, the center of this transverse passage communicating with an axial passage 576 one end of which serves as a seat for the check valve 154. The passage 138 in the valve member 102 is constituted by two passages 578 which are located on the opposite side of the check valve 154 from the passage 576.

Continuing to consider in detail the various passages in the valve member 102 and the valve body 106, the passage 136 in the valve member includes an axial bore 580, Fig. 31, and an axial counterbore 582, the bore 580 communicating with the passages 578 and the counterbore 582 communicating with the metering orifice 144 and with radial ports 584 leading to the external annular groove 134 in the valve member. As hereinbefore described, the annular groove 134 is connected to the annular groove 158 by the helical throttling groove 164. It will be noted that, in this embodiment, the helical throttling groove 132 and the corresponding annular groove 128 are omitted, which results in a slightly different mode of operation, as will be explained hereinafter.

Considering the passage 142 in the valve body 106, it includes, as shown in Figs. 31 and 32, radial ports 586 in the valve body tube 446, these radial ports communicating at their outer ends with longitudinal grooves 588 in the valve body tube. The grooves 588 extend upwardly to radial ports 590, Figs. 30 and 32, which communicate with the annular space 165 around the stem 126 when the valve member 102 is in its lower position. Under such conditions, the space 165 is exposed to the spent operating fluid pressure through the passage 166 hereinbefore described in detail. It will be noted that the valve body tube 446 is also provided with radial ports 592 and 594, Figs. 30 and 32, which communicate with the longitudinal grooves 588.

Considering the passage 162, it includes longitudinal grooves 598, Figs. 30 to 32, in the valve body tube 446, the ports 160, Figs. 30 and 32, connecting these grooves to the valve bore 104. The tube 446 is provided at the upper ends of the grooves 598 with ports 600 which communicate with external longitudinal grooves 602, Fig. 30, in the sleeve 450. These grooves communicate at their upper ends with notches 604 in a flanged upper

end of the sleeve 450, these notches communicating with an annular groove 606 in the fitting 448. The groove 606 is in constant communication with the operating fluid under pressure in the bore 292 through one or more ports 608 in the fitting 448. Thus, the longitudinal grooves 598 constantly contain operating fluid under pressure. It should be noted that the grooves containing the O-rings 456 and 458 communicate with the grooves 602 through ports 610 and 612, respectively, and that the groove containing the O-ring 460 communicates with the grooves 602 through the ports 600. Thus, the operating fluid pressure is always applied to the O-rings 456, 458 and 460 to bias them outwardly into engagement with the sealing sleeve 440.

The grooves 598 also form the passage 168, this passage terminating in radial ports 614, Figs. 31 and 32, in the valve body tube 446, which ports connect the grooves 598 to the valve bore 104.

Operation of valve unit 266

The operation of the valve unit 266 is virtually identical to that of the valve unit 94 of Figs. 5 and 6 of the drawings. Consequently, the operation of the valve unit 266 will be considered only briefly herein.

Considering movement of the valve member 102 of the valve unit 266 downwardly from its upper position to its lower position, such downward movement is initiated when the plunger 46 reaches the end of its upward stroke so that the annular channel 112 therein bridges the passages 114 and 116. This permits fluid to escape from below the valve member 102 to the return tubing 98 in the manner hereinbefore described, the valve member initially moving downwardly at its first speed. This first speed of downward movement of the valve member 102 terminates when the lower end of the valve member covers the ports 556, Fig. 31.

Considering the second speed of downward movement of the valve member 102, fluid from beneath the valve member flows upwardly through the passages 578, the bore 580, the counterbore 582, the radial ports 584, the annular groove 134, the helical throttling groove 164, the annular groove 158, the ports 592 and 594 and the passage 142 leading to the return tubing 98. Thus, the throttling groove 164 controls the second speed of downward movement of the valve member 102, thereby replacing the throttling groove 132 of Figs. 5 and 6 of the drawings.

Considering the third speed of downward movement of the valve member 102, the annular groove 140 therein ultimately registers with the ports 586, which communicate with the passage 142 leading to the return tubing 98. Under such conditions, fluid must escape from beneath the valve member 102 through the metering orifice 144, which determines the third speed of the valve member.

The upward movement of the valve member 102 of the valve unit 266 is identical to that of the valve member of the valve unit 94. Briefly, when the plunger 46 reaches the end of its downward stroke so that the annular channel 110 bridges the passages 108 and 116, operating fluid under pressure is applied to the lower end of the valve member 102 through the passage 116, the passage 148, the passage 152, the check valve 154, and the passage 138. Thus, the valve member moves upwardly at its first speed, until such time as the annular groove 150 therein moves upwardly out of register with the ports 568. At this point, the annular groove 158 in the valve member registers with the ports 160 so that operating fluid from the passage 162 flows downwardly to the lower end of the valve member through the ports 160, the annular groove 158, the throttling groove 164, the annular groove 134, the ports 584, the counterbore 582, the bore 580 and the passages 578. Under such conditions, the valve member 102 moves upwardly at its second speed, which is determined by the throttling groove 164. Thus, this one throttling groove controls the second

speed of the valve member 102 in both directions. The third speed of upward movement of the valve member 102 begins when the annular groove 140 therein registers with the ports 614 communicating with the operating fluid pressure through the passage 168. Under such conditions, the operating fluid under pressure flows to the lower end of the valve member 102 through the ports 614, the annular groove 140, the metering orifice 144, the counterbore 582, the bore 580 and the passages 578.

10 Thus, the valve member 102 moves upwardly at its third speed determined by the metering orifice 144.

Installation and removal of pump and valve units 264 and 266

15 As hereinbefore suggested, the pump and valve units 264 and 266 may be circulated into and out of the well in unison, or independently of each other. In order to install the pump and valve units 264 and 266, the closures 268 and 270 at the upper ends of the production and supply tubings 100 and 96, respectively, are removed and the pump and valve units are inserted into the production and supply tubings respectively, the closures then being replaced. If it is desired to circulate both the pump and the valve units 264 and 266 into the well simultaneously, 20 the control device 246 is set to connect the supply line 248 to both the production tubing 100 and the supply tubing 96. This results in the delivery of operating fluid to the production and supply tubings 100 and 96 above the pump and valve units 264 and 266 to displace these units downwardly through the production and supply tubings, respectively, into the pump and valve chambers 260 and 262, respectively. Since gravity assists in the downward movement of the pump and valve units 264 and 266, it is necessary to apply only a relatively low pressure above these units. Under such conditions, fluid 25 in the supply and production tubings 96 and 100 below the valve and pump units 266 and 264 is circulated to the surface through the return tubing 98, the control device 246 preferably connecting the return tubing to the production line 252 since the production tubing may contain foreign material. The fluid beneath the pump unit 264 may flow from the pump chamber 260 into the return tubing 98 through the ports 332, the annular groove 334, the passage 336, the bore 306, the tube 304 and the bore 302. The fluid below the valve unit 266 may flow from 30 the valve chamber 262 into the return tubing 98 through the seat 444, the tube 296, the bore 298, the passage 326, the annular groove 324, the ports 322, the annular groove 320, the annular groove 334, the passage 336, the bore 306, the tube 304 and the bore 302.

35 If the pump unit 264 is already in place in the pump chamber 260 and seated on the pump unit seat 342 when the valve unit 266 is circulated in, the fluid beneath the valve unit may be displaced into the production tubing 100. More particularly, the fluid beneath the valve unit flows through the valve unit seat 444, the tube 296, the bore 298, the passage 326, the annular groove 324, the ports 322, the annular groove 320, the annular groove 420 and the ports 422 into the coupling 412, and then flows upwardly through the standing valve 86, the working valve 74 and the standing valve 82 into the production tubing.

40 If the pump unit 264 is run in with the valve unit 266 in place in the valve chamber 262 and seated on the valve unit seat 444, fluid from beneath the pump unit escapes through the ports 332, the annular groove 334, the passage 336, the bore 306, the tube 304, and the passage 302 into the return tubing 98. Under such conditions, the control device 246 is preferably set to maintain pressure in the supply tubing 96 above the valve unit 266 to prevent unseating thereof while the pump unit 264 is being run in.

45 If the valve unit 266 is run in ahead of the pump unit 264, fluid from beneath the valve unit may be displaced

into either the return tubing 98 or the production tubing 100. Considering the former, fluid from beneath the valve unit flows through the valve unit seat 444, the tube 296, the bore 298, the passage 326, the annular groove 324, the ports 322, the groove 320, the pump chamber 260, the ports 332, the groove 334, the passage 336, the bore 306, the tube 304 and the bore 302 into the return tubing. Considering the latter, fluid from beneath the downwardly moving valve unit 266 flows through the valve unit seat 444, the tube 296, the bore 298, the passage 326, the annular groove 324, the ports 322 and the annular groove 320 into the pump chamber 260, and then flows upwardly through the pump chamber into the production tubing.

If the pump unit 264 is run in ahead of the valve unit 266, the fluid from beneath the pump unit is preferably displaced into the return tubing 98 to avoid contaminating the supply tubing 96, the manner in which the fluid from beneath the pump unit is displaced into the return tubing having been considered earlier herein.

Thus, it will be seen that the pump and valve units 264 and 266 may be run in simultaneously, that the pump unit 264 may be run in ahead of the valve unit, that the valve unit may be run in ahead of the pump unit, that the pump unit may be run in with the valve unit in place, and that the valve unit may be run in with the pump unit in place. The pump and valve units may be circulated out of the well in unison, or independently, in similar ways, as will now be considered.

First, it will be assumed that the pump and valve units 264 and 266 are in their operating positions and that it is desired to remove the valve unit without removing the pump unit. Under such conditions, the control device 246 is set to close the upper end of the production tubing 100 so that the pump unit will not be unseated, and the control device is also set to connect the supply line 248 to the return tubing 98. The operating fluid thus introduced into the return tubing 98 flows downwardly into the bore 302 and into a passage 620, Fig. 29, which connects the bore 302 to the valve bore 292 below the sealing sleeve 440. The fluid under pressure then flows downwardly to the lower end of the valve unit extension 328 and acts upwardly on the tapered lower end 442 of the extension to unseat the valve unit and move it upwardly into the supply tubing 96 and to the surface. Once the valve unit unseats, fluid is prevented from escaping downwardly through the tube 296, and thence upwardly through the valves of the pump unit 264, because of the fact that the upper end of the production tubing 100 is closed, as hereinbefore mentioned. The fluid under pressure applied below the valve unit 266 in the foregoing manner moves the valve unit upwardly to the surface rapidly since the supply tubing 96 is of relatively small diameter. Also, since the valve unit 266 is light in weight, no packer cup, comparable to the packer cup on the pump unit 264, is necessary to prevent fluid by-passing past the valve unit.

It will now be assumed that both the pump and valve units 264 and 266 are in their operating positions and that it is desired to remove the pump unit without removing the valve unit. Under such conditions, the control device 246 is set to close the upper end of the supply tubing 96 to prevent unseating of the valve unit, and the control device 246 is set to connect the supply line 248 to the return tubing 98. Under such conditions, fluid under pressure flows downwardly through the return tubing 98, the bore 302, the tube 304, the bore 306, the passage 336, the annular groove 334 and the ports 332 and acts on the lower end of the pump unit to unseat it and move it upwardly to insert the packer cup 356 into the production tubing 100. With a relatively low fluid level in the well, the pressure required to unseat the pump unit 264 in the foregoing manner is relatively high, e.g., as high as 1,000 pounds per square inch. Consequently, when the pump

unit unseats, it attains sufficient velocity, due to the sudden release of this relatively high pressure, to carry it upwardly several feet, which is more than sufficient to insert the packer cup 356 into the production tubing 100 to prevent fluid by-passing around the pump unit. However, if the fluid level in the well is close to the surface, the pressure required to unseat the pump unit 264 may be quite low. Under such conditions, the pump unit may not acquire sufficient velocity, upon release of the unseating pressure, to carry it upwardly far enough to insert the packer cup 356 into the production tubing 100. If this were to occur, the pressure applied beneath the pump unit could then by-pass the pump unit through the valves 86, 74 and 82 and around the packer cup, with the result that the pump unit would merely unseat and then would not move upwardly any farther. To prevent this, the pump unit 264 may be provided with an extension 622, Fig. 33, projecting downwardly into an elongated standing valve assembly 341 with a relatively small clearance between the extension 622 and the interior of the standing valve assembly. With this construction, fluid pressure applied below the pump unit cannot be dissipated through the valves of the pump unit until the extension 622 is withdrawn from the standing valve assembly 341. By making the extension 622 sufficiently long that it is not withdrawn from the standing valve assembly 341 until the packer cup 356 enters the production tubing 100, any possibility of by-passing through the valves of the pump unit and around the packer cup upon unseating of the pump unit is eliminated. The extension 622 does not need to make a fluid-tight fit in the standing valve assembly 341 since the amount of fluid available to remove the pump unit is sufficient to produce a pressure drop, by leakage through the fit between the extension 622 and the standing valve assembly 341, which is more than the pressure required to balance the weight of the pump unit. Consequently, the pump unit will move upwardly to the point where the packer cup 356 enters the production tubing 100.

If both the pump unit 264 and the valve unit 266 are to be removed from the well simultaneously, the control device 246 is set to connect the supply line 248 to the return tubing 98 and, initially, is preferably set to close the upper end of the supply tubing 96. The reason for the latter is that the pressure required to unseat the pump unit 264 is much greater than that to unseat the valve unit 266. Once the pump unit 264 has been unseated and started on its way up the production tubing 100, the upper end of the supply tubing 96 may be opened to permit the valve unit 266 to move upwardly at the same time. As an alternative to closing the upper end of the supply tubing 96 initially when removing the pump and valve units 264 and 266 simultaneously, the control device 246 may merely be set to throttle flow out of the supply tubing 96 sufficiently to insure unseating of the pump unit. Preferably, such throttling of the flow out of the upper end of the supply tubing 96 is continued to insure simultaneous upward movement of the pump and valve units 264 and 266, since the valve unit will tend to move upward more readily than the pump unit.

If it is desired to remove the valve unit 266 after the pump unit 264 has been removed, the control device 246 is set to close the upper end of the production tubing 100 and to connect the supply line 248 to the return tubing 98. Under such conditions, the fluid pressure acts on the lower end of the valve unit in the manner hereinbefore described to unseat it and move it upwardly through the supply tubing 96, closure of the upper end of the production tubing 100 preventing the escape of fluid pressure into the production tubing.

Similarly, if it is desired to remove the pump unit 264 after the valve unit has been removed, the control device 246 is set to close the upper end of the supply tubing 96 and to connect the return tubing 98 to the supply

line 248, the production tubing 100 also being connected to the production line 252. Under these conditions, fluid pressure is applied to the lower end of the pump unit 264 in the manner hereinbefore described to unseat it and move it upwardly through the production tubing 100, the escape of fluid pressure into the supply tubing 96 being prevented by closing the upper end of this tubing.

Thus, it will be seen that the pump and valve units 264 and 266 may be removed from the well simultaneously, that the valve unit 266 may be removed ahead of the pump unit, that the pump unit may be removed ahead of the valve unit, that the valve may be removed after the pump unit has been removed and that the pump unit may be removed after the valve unit has been removed.

As hereinbefore pointed out, an important feature of the present invention is that it permits removal of the valve unit 266 without any necessity for removing the pump unit 264, which is desirable since wear of the valve unit occurs at a much higher rate than wear of the pump unit. Thus, the valve unit may be removed for repair or replacement without disturbing the pump unit, and the removal of the valve unit may be accomplished in a short period of time, as compared to the time required for removing the pump unit is of small diameter and light in weight. Thus, whenever the valve unit 266 requires repair or replacement, a pump can circulate the worn valve out and a replacement valve unit in in a very short period of time. This is an important feature since it materially reduces the down time of the well, as compared with an installation wherein the pump and valve units are incorporated in a single unit.

Another important feature is that the valve unit 266 is never exposed to the production fluid, and thus is not exposed to any contaminants which may be present therein, or any corrosion products in the production tubing 100. As will be apparent, when the valve unit 266 is circulated out of the well, nothing but clean operating fluid from the return tubing 98 is introduced thereunder. Similarly, the valve unit is circulated into the well with nothing but clean operating fluid. It will be noted that while fluid from the production tubing 100 may enter the return tubing 98 as the result of running the pump unit 264 into the well, any contaminants which may be introduced into the return tubing as a result of this will be cleared out of the return tubing by subsequent operation of the pump. Consequently, the return tubing is ultimately filled with clean operating fluid for subsequent removal of the valve unit.

While Figs. 15 to 32 of the drawings have been devoted to pump and valve units 264 and 266 corresponding to the pump and valve units illustrated in Figs. 5 and 6 of the drawings, it will be understood that pump and valve units corresponding to those illustrated in Figs. 7 to 14 of the drawings may be substituted. Also, various other combinations, using the same valve unit 266, may be attained by substituting different combinations of valve rods and packer collar sleeves for the valve rod 58 and the packer collar sleeve 316.

Although I have disclosed exemplary embodiments of my invention herein for purposes of illustration, it will be understood that various changes, modifications and substitutions may be incorporated in the embodiments disclosed without departing from the spirit of the invention as defined by the claims hereinafter appearing.

I claim as my invention:

1. In a fluid operated pump for a well, the combination of: a fluid operated pump unit located in the well and including a pump body having therein reciprocable, interconnected engine and pump piston means; and a separate engine valve unit located in the well and spaced from said pump unit and including a valve body which is movable vertically relative to said pump body and which has therein movable engine valve means for controlling the application and direction of a fluid pressure

differential to said engine piston means to reciprocate said engine and pump piston means.

2. In a fluid operated pump for a well, the combination of: a fluid operated pump unit located in the well and including a pump body having therein reciprocable, interconnected engine and pump piston means, said engine and pump piston means being reciprocable in said pump body by a fluid pressure differential applied to said engine piston means; and a separate engine valve unit located in the well out of axial alignment with said engine and pump piston means and including a valve body which is movable vertically relative to said pump body and which has therein movable engine valve means for controlling the application and direction of a fluid pressure differential applied to said engine piston means so as to axially reciprocate said engine and pump piston means.

3. In a fluid operated pumping system, the combination of: a fluid operated pump unit disposed in a well and including a pump body having therein reciprocable, interconnected engine and pump piston means; a separate fluid operated valve unit disposed in the well and spaced from said pump unit, said valve unit including a valve body which is movable vertically relative to said pump body and which has therein movable engine valve means for controlling the application and direction of a fluid pressure differential to said engine piston means to reciprocate said engine and pump piston means; means, including a supply tubing set in the well, for conveying operating fluid under pressure downwardly to said units; and means for conveying production fluid discharged by said pump piston means and spent operating fluid upwardly from said units.

4. In a fluid operated pumping system, the combination of: pump and valve tubings set in a well; means connecting the lower ends of said pump and valve tubings in fluid communication; a fluid operated pump unit movable through said pump tubing into an operating position in the well, said pump unit including interconnected engine and pump piston means; and a fluid operated valve unit movable through said valve tubing into an operating position in the well adjacent said operating position of said pump unit, said valve unit including engine valve means for controlling the application and direction of a fluid pressure differential to said engine piston means to reciprocate said engine and pump piston means.

5. In a fluid operated pumping system, the combination of: pump and valve tubings set in a well; means connecting the lower ends of said pump and valve tubings in fluid communication; a fluid operated pump unit movable through said pump tubing into an operating position in the well, said pump unit including interconnected engine and pump piston means; a fluid operated valve unit movable through said valve tubing into an operating position in the well adjacent said operating position of said pump unit, said valve unit including engine valve means for controlling the application and direction of a fluid pressure differential to said engine piston means to reciprocate said engine and pump piston means; means for hydraulically moving said pump unit upwardly from its operating position in the well through said pump tubing to the surface; and means for moving said valve unit hydraulically from its operating position in the well upwardly through said valve tubing to the surface.

6. In a fluid operated pumping system, the combination of: a bottom hole assembly set in a well and providing a valve chamber; a valve tubing set in the well and communicating with said valve chamber; a fluid operated pump unit in said bottom hole assembly and communicating with said valve chamber, said pump unit including interconnected engine and pump piston means; and a fluid operated valve unit separate from said pump unit and movable between the surface and said valve chamber through said valve tubing, said valve unit including engine valve means for controlling the applica-

tion and direction of a fluid pressure differential to said engine piston means to reciprocate said engine and pump piston means.

17. A fluid operated pumping system as defined in claim 6 wherein said bottom hole assembly is provided with a pump chamber to receive said pump unit, and wherein a pump tubing is set in the well in communication with said pump chamber, said pump unit being movable between the surface and said pump chamber through said pump tubing.

8. In a fluid operated pumping system, the combination of: a fluid operated pump including a fluid operated pump unit and a separate, fluid operated engine valve unit for controlling the operation of said pump unit, said pump unit including a pump body having therein reciprocable, interconnected engine and pump piston means, and said valve unit including a valve body which is movable vertically relative to said pump body and which has therein movable engine valve means for controlling the application and direction of a fluid pressure differential to said engine piston means to reciprocate said engine and pump piston means; and means for moving said pump and valve units between the surface and operating positions in a well independently of each other.

9. In a fluid operated pump for a well, the combination of: a fluid operated pump unit located in the well and including a pump body having therein fluid operated engine means and pump means operated by said engine means; and a separate engine valve unit located in the well and spaced from said pump unit and including a valve body which is movable vertically relative to said pump body and which has therein movable engine valve means for controlling the operation of said engine means.

10. A bottom hole assembly for a fluid operated well pump having separate pump and engine valve units, comprising a housing having therein pump and valve chambers for said pump and valve units, respectively, said pump and valve chambers having open upper ends to provide for insertion of said pump and valve units into and withdrawal thereof from said pump and valve chambers, respectively, independently of each other when said housing is disposed in a well with said open upper ends of said chambers uppermost, and said housing having therein passage means interconnecting said chambers, said pump unit including a pump body having therein reciprocable, interconnected engine and pump piston means, and said valve unit including a valve body which is movable vertically relative to said pump body and which has therein movable engine valve means for controlling the application and direction of a fluid pressure differential to said engine piston means to reciprocate said engine and pump piston means.

11. A bottom hole assembly for a fluid operated well pump having separate pump and engine valve units, including a housing having therein pump and valve chambers for said pump and valve units, respectively, said pump and valve chambers being side-by-side and laterally spaced apart, said pump and valve chambers having open upper ends to provide for insertion of said pump and valve units into and withdrawal thereof from said pump and valve chambers, respectively, independently of each other when said housing is disposed in a well with said open upper ends of said chambers uppermost, and said housing having therein passage means interconnecting said pump and valve chambers, said pump unit including a pump body having therein reciprocable, interconnected engine and pump piston means, and said valve unit including a valve body which is movable vertically relative to said pump body and which has therein movable engine valve means for controlling the application and direction of a fluid pressure differential to said engine piston means to reciprocate said engine and pump piston means.

12. In a fluid operated pumping system, the combina-

tion of: a housing having therein a valve chamber; a fluid operated pump unit adapted to be positioned in said housing in communication with said valve chamber and having interconnected engine and pump piston means;

5 and a separate, free, fluid operated valve unit movable into and out of said valve chamber and including engine valve means for controlling the application and direction of a fluid pressure differential to said engine piston means, when said valve unit is in said valve chamber, to reciprocate said engine and pump piston means.

13. A free, fluid operated engine valve unit movable through a valve tubing into an operating position adjacent a fluid operated pump unit having reciprocable, interconnected engine and pump piston means, said valve unit including an elongated, cylindrical valve body of a diameter less than and movable through said valve tubing and including a valve member movable in said valve body and having means for controlling the application and direction of a fluid pressure differential to said engine piston means to reciprocate said engine and pump piston means.

14. In a fluid operated pump for a well, the combination of: a pump unit located in the well and including interconnected engine and pump piston means having an axial passage therethrough for the flow of fluid pumped by said pump piston means; and a separate engine valve unit located in the well out of axial alignment with said passage and including engine valve means for controlling the application and direction of a fluid pressure differential to said engine piston means to reciprocate said engine and pump piston means, said valve unit including a valve body in which said engine valve means is disposed and which is movable vertically relative to said pump unit.

15. In a fluid operated pump for a well, the combination of: a pump unit located in the well and including interconnected engine and pump piston means having an axial passage therethrough for the flow of fluid pumped by said pump piston means; and a separate engine valve unit located in the well alongside of said engine and pump piston means and including engine valve means for controlling the application of a fluid pressure differential to said engine piston means so as to reciprocate said engine and pump piston means, said valve unit including a valve body in which said engine valve means is disposed and which is movable vertically relative to said pump unit.

16. A fluid operated pump as defined in claim 15 including a working valve carried by said engine and pump piston means in said passage, said pump including an inlet and an outlet which communicate with the respective ends of said passage and one of which is provided with a standing valve controlling flow therethrough.

17. In a fluid operated pump actuatable by operating fluid at a higher pressure and discharge spent operating fluid at a lower pressure, the combination of: combined engine and pump piston means incorporated in a single plunger movable through working and return strokes, said plunger being provided with an axial passage therethrough for production fluid pumped by said pump piston means, said plunger having an intermediate section of reduced diameter to provide transverse areas facing each other and forming said engine piston means, that one of said transverse areas which faces in a direction opposite the direction of movement of said plunger during said return stroke being slightly larger than the other of said areas; a working valve carried by said plunger and controlling flow through said passage; means providing an inlet and an outlet for production fluid which communicate with the respective ends of said plunger and at least one of which is provided therein with a standing valve controlling flow of production fluid therethrough; means for constantly applying one of said pressures to one of said areas; and engine valve means located alongside of and spaced laterally from said plunger for alternately applying said higher pressure and said

lower pressure to the other of said areas, whereby to produce said strokes of said plunger alternately.

18. In a fluid operated pump, the combination of: a plunger having an intermediate section of reduced diameter and providing different transverse areas facing each other; and means for producing reciprocatory movement of said plunger, including engine valve means for alternately applying high and low pressures to one of said areas and one of said pressures constantly to the other of said areas.

19. A fluid operated pump according to claim 18 wherein said plunger is provided with an axial passage therethrough for the flow of production fluid and wherein said engine valve means is located alongside of and spaced laterally from said plunger.

20. A fluid operated pump unit including: a cylinder; a plunger element reciprocable in said cylinder; means for admitting operating fluid under pressure into said cylinder on at least one side of said plunger element; means providing an annular space encircling said cylinder, said cylinder forming the inner wall of said annular space; and means for admitting said operating fluid into said annular space to balance the pressure acting radially inwardly and outwardly on said cylinder.

21. A fluid operated pump unit including: a cylinder; 25

a plunger element reciprocable in said cylinder; means for applying pressures of different magnitudes to the ends of said plunger element; and means for applying to the entire exterior of said cylinder a pressure equal to higher than the higher of said pressures applied to the ends of said plunger element.

UNITED STATES PATENT OFFICE
CERTIFICATION OF CORRECTION

Patent No. 2,949,857

August 23, 1960

Clarence J. Coberly

It is hereby certified that error appears in the above numbered patent requiring correction and that the said Letters Patent should read as corrected below.

Column 8, line 19, for "punger" read -- plunger --; column 9, line 56, for "included" read -- includes --; column 38, line 5, strike out "higher than".

Signed and sealed this 27th day of June 1961.
